ELEVATOR SYSTEM

John Lusti, River Vale, N.J., and William Frank Glaser, Eastchester, N.Y., assignors to Otis Elevator Company, New York, N.Y., a corporation of New Jersey

Filed Mar. 13, 1959, Ser. No. 799,197

70 Claims. (Cl. 187—29)

The invention relates to elevator systems.

In many types of buildings, the space occupied by the elevators is an important factor. There have been many improvements made with the view of increasing the passenger handling capacity of elevators so as to reduce the number of elevators required for the installation. Among these is the provision of multicompartment cars such as in the patent to Lindquist et al., No. 1,997,260, granted April 9, 1935. In the arrangement set forth in this patent, which is specifically illustrated for double compartment cars, the compartments serve alternate floors, the bottom compartment serving say odd numbered floors and the top compartment even numbered floors. Inasmuch as many of the stops made involved passenger transfer for both compartments, this arrangement considerably reduced the total number of stops made and thus gave increased traffic handling capacity without an increase in the space required for the elevators. The present invention is directed to multicompartment elevators.

The principal object of the invention is to provide an improved multicompartment elevator system. More specifically, an object of the invention is to provide a multicompartment elevator system in which the number of stops for each round trip of the car is further reduced.

The features, advantages and operation of the system will be set forth as applied to double compartment cars, but it is to be understood that in many instances they also apply to cars having a greater number of compartments.

The invention in one of its principal aspects is directed to the manner in which intermediate floors are served. In the system to which the invention is illustrated as applied, up landing call registering means and down landing call registering means are provided for each of the intermediate floors. Also car call registering means are provided for each of the intermediate floors within each compartment. Where a compartment makes a stop at a floor in response to a landing call for that floor under conditions where its car call for that floor is also registered, this car call is also answered in making the stop.

The invention involves having one compartment respond to up landing calls during an up trip and the other compartment to respond to down landing calls during a down trip. However, where landing calls for the direction of car travel are registered for two adjacent floors, or a landing call for the direction of car travel is in registration for a floor and a car call for the leading compartment is in registration for the floor next beyond or a car call for the following compartment is in registration for the next preceding floor, but one stop is made to answer such calls, regardless of for which pair of adjacent floors such calls are registered. Also where a car call is registered for the compartment, other than the one which responds to the landing calls for the direction of car travel, for the same floor for which a landing call for that direction is registered, such other compartment responds to both calls so that again but

2

one stop is made to answer such calls, regardless of for which floor such calls are registered.

In carrying out the invention according to one arrangement, the top compartment is caused to respond to up landing calls on the up trip and the bottom compartment to down landing calls on the down trip. Where up landing calls are in registration for two adjacent floors, the top compartment on its upward trip is caused to bypass the lower of the two calls and both calls are answered with but a single stop by stopping the car with the bottom compartment at the lower and the top compartment at the upper of the two floors, without regard to odd and even numbered floors. Also, where the top compartment has a car call for the floor next above the 15 one for which an up landing call is registered or where the bottom compartment has a car call for the same floor for which an up landing call is registered, these calls are answered on the up trip, in each case with but a single stop with the bottom compartment at the floor 20 at which the up landing call is registered. Similarly, where down landing calls are in registration for two adjacent floors, the bottom compartment on the down trip is caused to bypass the upper of the two calls and the calls are answered with but a single stop by stopping the 25 car with the top compartment at the upper and the bottom compartment at the lower of the two floors, without regard to odd or even numbered floors. Also, where the bottom compartment has a car call for the floor next below the one for which a down landing call is registered or where the top compartment has a car call for the same floor for which a down landing call is registered, these calls are answered on the down trip, in each case with but a single stop with the top compartment at the floor at which the down landing call is registered. 35 In carrying out the invention according to another arrangement, the bottom compartment is caused to respond to up landing calls on the up trip and the top compartment is caused to respond to down landing calls on the down trip. Where up landing calls are in registration for two adjacent floors, again the calls are answered with but a single stop by causing, when the bottom compartment picks up the lower of the two calls on the up trip, the top compartment to respond to the upper of the two calls, regardless of the pair of floors involved. Also, where the bottom compartment has a car call for the floor next below the one for which an up landing call is registered or the top compartment has a car call for the same floor for which an up landing call is registered, these 45 calls are answered on the up trip, in each case with but a single stop with the top compartment at the floor for which the up landing call is registered. Similarly, when down landing calls are in registration for two adjacent floors, the calls are answered with but a single stop by causing, when the top compartment picks up the upper of the two calls on the down trip, the bottom compartment to respond to the lower of the two calls, regardless of the pair of floors involved. Also, where the top compartment has a car call for the floor next above the one for which a down landing call is registered or the bottom compartment has a car call for the same floor for which a down landing call is registered, these calls are answered on the down trip, in each case with but a single stop with the bottom compartment at the floor for which the down landing call is registered. 55 Thus, with either of the above arrangements, where landing calls, or a landing call and compartment car call, calling for stops at adjacent floors are registered, but one stop is made in response to both calls, regardless of which adjacent floors are involved. Also, but one stop is made where a compartment car call is registered for the same floor for which a landing call is registered for the direc- 60 65 70

tion of car travel, regardless of the floor for which the calls are registered. This reduces the number of total stops made over that in an alternate floor stop system where, in case of calls for adjacent landings, two stops are made if the farther call is for a floor not served by the leading compartment in response to landing calls, regardless of whether or not each compartment serves all floors in response to car calls and where, in case of a compartment call for the same floor as a landing call for the direction of car travel, two stops are made if the floor is not served in response to landing calls by the compartment having the car call.

The invention also involves, as a modified arrangement, causing one compartment to bear the brunt of the service. For example, the top compartment may be caused to respond to the up landing calls on the up trip and to the down landing calls on the down trip, or the bottom compartment may be caused to respond to the up landing calls on the up trip and to down landing calls on the down trip, in each case subject to the exceptions above noted, as for example where calls are in registration for adjacent floors, where a single stop is made in answering more than one call.

In the arrangements described for carrying out the invention, the car, under certain conditions, may be caused on its upward trip to stop and reverse at the floor of highest call. Such highest call may be a down landing call or a car call for either compartment. Where the highest call is a down call or a car call for the top compartment, the high call reversal stop is made by the top compartment in response to this call, regardless of the floor for which such call is registered and also regardless of whether the system is arranged for answering the up landing calls by the top compartment or the bottom compartment. If under such conditions a down landing call is in registration for the floor next below the one at which the high call reversal stop is being made, the bottom compartment answers this call so that but one stop is made. When the highest call is a car call for the bottom compartment, the high call reversal stop is made by the bottom compartment at the floor for which the car call is registered. Should a down landing call be in registration for the same floor, this call also is answered by the bottom compartment so that again but one stop is made.

Under high call reversal conditions, the arrangement in which the top compartment is caused to respond to up landing calls on the up trip is of advantage over the arrangement in which the bottom compartment responds to these calls in that with the arrangement in which the top compartment serves the calls, it will pick up the majority of the up landing calls on the upward trip and as a consequence it has a greater chance of having the highest car call. Under such conditions the car would be reversed at one floor lower than it would if the bottom compartment had the highest car call.

The manner in which the compartments respond to calls at the terminals may vary. The system may be arranged so that on its downward trip the bottom compartment does not stop at the upper lobby, or does not do so under certain conditions, and on its upward trip does not stop at the upper lobby or does so only under certain conditions.

As a modification, the system may be arranged so that the calls for the direction of car travel are always picked up by the leading compartment, except where the call is registered too late, in which case it is picked up by the following compartment.

The control for the compartments may be arranged to provide automatic bypass of landing calls by each compartment when it is carrying over a certain load and the circuits are shown to provide this operation. With this arrangement, in accordance with the invention, when a compartment is sufficiently loaded automatically to bypass landing calls which it would otherwise pick up, the other compartment picks up such calls. This applies to any of the above discussed arrangements and also to an alternate floor stop system.

There are various features of the invention relating to operation of compartment doors, some of which will be seen from the detailed description. Among these are the control of the doors of one compartment, dependent on the condition of the doors of the other compartment. The present invention contemplates control of the doors so as to insure a maximum traffic handling capacity with a minimum of stops, thereby increasing the elevator service without increasing the space required for the elevators. The manner in which this is obtained may vary depending upon the requirements of the particular installation. This control involves the opening, reopening and/or maintaining open of the doors of one compartment in response to the registering of the landing call for the direction of car travel for the floor at which such compartment is stopped, so long as the doors of the other compartment in opening have not reached a certain position, or the passenger transfer time interval has not expired or, even though the interval has expired, provided the doors for the other compartment in closing have not reached a certain position. Even though the doors for the other compartment in closing have reached such certain position, the doors of such one compartment may be reopened provided that in closing they have not reached a certain position. It also involves holding up the closing of the doors for one compartment by the holding up of the closing of the doors for such other compartment. This may be effective up to the time the passenger transfer time interval expires, or as an alternative, thereafter if the holding up of the doors is initiated before the passenger transfer time interval expires.

Other features and advantages of the invention will be seen from the following description and appended claims.

In the drawings:

Figures 1 to 8 inclusive taken together constitute a simplified "across-the-line" diagram of control circuits for a double compartment elevator and its hall lanterns;

Figure 9 is a circuit detail of a modification of a portion of the circuits of Figures 1 to 8; and

Figures 10a to 10c are key sheets for Figures 1 to 9 inclusive, showing the electromagnetic switches in spindle form.

The circuits are shown in a simplified manner to facilitate an understanding of a preferred mode of carrying out the invention. In this connection, it is to be understood that elevator control systems are very complex and that certain amplifications and alterations may be in order in adapting the invention to certain of these systems. The invention will be described as applied to a system in which the compartments are operated without attendants, but it is to be understood that certain aspects of the invention are applicable to other types of systems. While the description is directed principally to the operation of a single car with top and bottom compartments, it will be seen that in most instances, the car is but one of a plurality of multideck elevator cars subject to group control.

The electromagnetic switches employed in the system illustrated are designated as follows:

60 ACS—Advance call switch

ADV—Advanced brush switch

ALR—Advance lobby switch

ALT—Alternate floor switch

BCO—Bottom compartment out of service switch

65 BCS—Bottom compartment car call pickup switch

BDO—Bottom compartment door open switch

BDT—Bottom compartment door time switch

BHS—Bottom compartment landing call pickup switch

BLS—Bottom compartment load switch

70 BOT—Bottom compartment initial time switch

BTL—Below the lobby switch

CAZ—Car call advanced zone switch

CCB—Car call below switch

CNLS—No lobby car call stop switch

75 CZ—Car call zone switch

DDS—Down dispatch switch
 DIS—Dispatch switch
 GO—Preparatory to run switch
 H—Run switch
 HAZ—Landing call advanced zone switch
 HCC—Highest car call switch
 HNLS—No lobby landing call stop switch
 HUD—Highest landing call switch
 HZ—Landing call zone switch
 MG—Motor generator switch
 ML—Main landing switch
 NAC—No available lobby car switch
 OD—Down operation switch
 OU—Up operation switch
 P—Potential switch
 PCB—Preparatory call below relay
 SB—Start switch
 SLS—Total load switch
 SP—Speed switches
 ST—Stop switch
 TCO—Top compartment out of service switch
 TCS—Top compartment car call pickup switch
 TDO—Top compartment door open switch
 TDTS—Top compartment door time switch
 THL—Top landing switch
 THS—Top compartment landing call pickup switch
 TLS—Top compartment load switch
 TOT—Top compartment initial time switch
 UD—Direction control switch
 UFR—Up to down reversal switch
 ULD—Upper lobby down landing call relay
 UTLC—Up travelling loaded car switch
 VB—Bottom terminal car availability switch
 VD—Down traffic switch
 VDP—Down peak switch
 VN—Night service switch
 VT—Top terminal car availability switch
 VUP—Up peak switch
 WB—Bottom terminal selection switch
 WBX—Up dispatch holding switch
 WT—Top terminal selection switch
 WTS—Top terminal starting switch
 WTX—Auxiliary top terminal selection switch
 XBHS—Auxiliary bottom compartment landing call pickup switch
 XTHS—Auxiliary top compartment landing call pickup switch

Throughout the description which follows, these letters will be applied to the respective switch coils and, with reference numerals appended thereto, they will be applied to their respective switch contacts. The circuits are shown principally for but one elevator but, in certain instances where control switches for other elevators of the installation are involved, differentiation between the elevators is made by appending to the designating characters lower case letters *a*, *b*, *c* and *d* indicative of the different elevators. The location of the coils and contacts may be found from the key sheets of Figures 10a to 10c wherein the switches are arranged in alphabetical order with the coils and contacts positioned on spindles in horizontal alignment with their positions in the particular wiring diagram. They are related to the wiring diagrams by applying to the particular coil or contact the number of the figure in which it occurs, this being appended following a dash to the particular designation for the coil or contact. Thus to locate contacts ACS3 for example, referring to spindle sheet Figure 10a, it will be found that contacts number 3 of switch ACS have applied thereto following a dash the numeral 5. This means that these contacts appear in Figure 5. The contacts may then be located by aligning the sheet on which Figure 5 appears with the sheet on which Figure 10a appears and will be found in alignment with their position on Figure 10a.

The electromagnetic switches are illustrated in deen-

ergized condition. Each of switches BOT and TOT has both an operating coil and a holding coil. Switch ACS has two operating coils. Of the above listed switches, for convenience the circuits for the coils of switches ML, THL, 5 VB, VD, VDP, VN, VT, VUP, WB, WBX, WT, WTS and WTX are not shown, it being understood that the circuits for these coils may be controlled in accordance with the control of the coils of the corresponding switches in the patent to Glaser and Hornung No. 2,589,242, granted 10 March 18, 1952. The circuit for the coil of switch ML is completed when both compartments are at the lobbies. The circuit for the coil of switch THL is completed when both compartments are at the two top floors.

The coil of the electromechanical brake is designated 15 BR. As indicated in Figure 1, the brake is applied to the brake drum on the shaft 2 of the hoisting motor which drives the sheave 3 for raising and lowering the elevator car, having top compartment T and bottom compartment B, and the counterweight 5 for the car. The hoisting motor is illustrated as a direct current motor, its armature being designated MA and its field winding MF. The hoisting motor armature is illustrated as supplied with current at variable voltage by the armature GA of the generator of a motor generator set. The separately excited 20 field winding of the generator is designated GMF and the series field winding is designated GSF. GFAR is a resistor for controlling the strength of generator field winding GMF for acceleration while GFRR is a resistor for controlling the strength of the generator field winding 25 30 for retardation.

The driving motor of the motor generator set is not shown but an exciter, which may be driven by the driving motor, is illustrated for supplying current for certain of the circuits. The exciter armature is designated EAM, 35 its shunt field winding EMF and its series field winding ESF. In addition to the exciter for supplying current to certain of the control circuits, other control circuits are fed from separate supply lines designated + and -, not subject to the exciter. HL1 and HL2 are the supply 40 lines for the hall lantern circuits. These lines may be connected to an alternating current source. Also, additional supply lines designated B+ and B are provided for the call registration and pickup circuits.

Mechanism actuated in accordance with car movement 45 is utilized, and this may be in the form of a selector such as shown in the aforesaid patent to Glaser and Hornung, in which case switches 1SCC, 2SCC, 3SCC, 4SCC and 5SCC would be operated by cams 22, one for each switch, of that patent in the listed sequence during starting and acceleration and in the reverse sequence during retardation 50 and stopping. A circuit is shown for the advancer motor which operates cams to close the switches incident to the starting of the car. At the same time the advancer motor advances a panel, termed advancer panel, to place it in an advanced position with respect to the car. The armature of the advancer motor is designated AM and its field winding AMF. The cams are operated in the reverse sequence to open the switches during retardation by pawls which engage stopping collars for floors at which stops 55 are to be made. The extension and retraction of the pawls is controlled by the selector stopping magnet SM as explained in the patent.

The selector is also provided with stationary contacts 60 adapted to be engaged by movable contacts. Referring to Figure 5, one column of stationary contacts is provided for the up landing call pickup circuit. These contacts, which are provided one for each of the landings for which up landing calls are registerable, are designated generally as UH. Another column of stationary contacts is provided for the down landing call pickup circuits. These contacts, which are provided one for each of the landings for which down landing calls are registerable, are designated generally as DH. A third column of stationary contacts, one for each landing and designated generally 65 as DHH, is provided in the highest down landing call

rectifier stack circuit DRSC. A fourth column of stationary contacts, one for each landing and designated generally as UHH, is provided in the highest up landing call rectifier stack circuit URSC. Referring to Figure 6, another column of stationary contacts, one for each landing and designated generally as TCP, is provided for the top compartment car call pickup circuits. Still another column of stationary contacts, one for each landing and designated generally as BCP, is provided for the bottom compartment car call pickup circuits. Referring to Figure 7, a sixth column of stationary contacts, one for each landing plus one and designated generally as HZC, is provided for the landing call zoning circuits. A seventh column of stationary contacts, one for each landing plus one and designated generally as CZC, is provided for the car call zoning circuits. Referring to Figure 8, two other columns of stationary contacts, designated generally as ULC and DLC are provided for the hall lantern circuits. Referring back to Figure 6, a column of hook switches, one for each landing plus one and designated generally at HC, is provided for the highest car call circuit HCSC. The stationary contacts in each column are spaced in accordance with the distance between floors and are differentiated by numbers in accordance with the landings for which they are provided. Inasmuch as the hook switches serve for the landings in groups of two, they are differentiated in accordance with the pairs of landings for which they are provided.

Contacts UH are adapted to be engaged by three brushes movable in accordance with car movement. The upper brush TLUAB, which is the top compartment up landing call advance brush, is positioned to be in engagement with the stationary contact for the landing next above the ones in which the compartments are stopped. The middle brush TUB, which is the top compartment up landing call pickup brush, is positioned to be in engagement with the stationary contact for the landing at which the top compartment is stopped. The lower brush BUB, which is the bottom compartment up landing call pickup brush, is positioned to be in engagement with the stationary contact for the landing at which the bottom compartment is stopped. Contacts DH are adapted to be engaged by three similar brushes, namely the lower brush BLDAB, which is the bottom compartment down landing call advance brush, the middle brush BDB which is the bottom compartment down landing call pickup brush and the upper brush TDB which is the top compartment down landing call pickup brush. A top compartment brush TDHB and a bottom compartment brush BDHB are provided for engaging contacts DHH, and a top compartment brush TUHB and the bottom compartment brush BUHB are provided for engaging contacts UHH. Brush BDHB is mounted on a lever for effecting the separation of contacts HHC when the brush engages a stationary contact. Three brushes, namely up advance brush TCUAB, pickup brush TCB and down advance brush TCDAB, are provided for engaging stationary contacts TCP. Similarly, down advance brush BCDAB, pickup brush BCB and up advance brush BCUAB are provided for engaging contacts BCP. Three brushes, namely up advance brush UHZB, middle brush HZB and down advance brush DHZB, are provided for engaging stationary contacts HZC. Similarly, up advance brush UCZB, middle brush CZB and down advance brush DCZB are provided for engaging contacts CZC. A top compartment brush TULB and a bottom compartment brush BULB are provided for engaging contacts ULC and a top compartment brush TDLB and a bottom compartment brush BDLB are provided for engaging contacts DLC. An insulating cam CHC is provided for operating hook switches HC. All of these brushes and the cam are mounted on the advancer panel. Certain of the brushes, namely brushes TLUAB, BLDAB, TDHB, BDHB, TUHB, BUHB, TCUAB, TCDAB, BCUAB, BCDAB, UHZB, HZB, DHZB, UCZB, CZB and DCZB are elongated as

indicated. Other stationary contacts and cooperating contacts are mounted on the selector, as will be seen as the description proceeds.

The doors are indicated schematically in Figure 1. TCD is the top compartment car door and BCD is the bottom compartment car door. Hoistway doors are designated HD and are indicated as operated by being coupled to the car doors. The armature of the top compartment door operating motor is designated TDMA and its field winding TDMF. The armature of the bottom compartment door operating motor is designated BDMA and its field winding BDMF. TGC and BGC designate respectively the top compartment and bottom compartment door contacts. DS are indicative of hoistway door interlock contacts, but two being illustrated. TDOB and BDOB are door open buttons for the top and bottom compartments respectively. TDCL and TDOL are top compartment door close and door open limit switches respectively. BDCL and BDOL are similar switches for the bottom compartment door. DZ1 and DZ2 are door zone switches which are closed when the compartments are within a certain distance of the landings at which the stops are made.

A plurality of knife switches is illustrated for changing operations. These switches are designated generally as K and differentiated by appended numerals. Similarly resistors are generally designated as R, rectifiers as Y and capacitors as C. The up hall lanterns are designated UHL and the down hall lanterns are designated DHL, differentiation being made by numerals indicative of the landings for which they are provided. BDPD and TDPD are door detector contacts for the bottom and top compartment car doors respectively. They may be contacts operated in any suitable manner as, for example, by yieldable safety edges on the doors or electronically as disclosed in the patent to Bruns No. 2,601,250, granted June 24, 1952. TLW and BLW are load weighing switches for the top and bottom compartments respectively. Various safety devices are indicated by the block having the legend "safeties."

Referring to Figures 5 and 6, while the calls may be registered in any suitable manner, the circuits are illustrated for registering the landing calls on electronic tubes U and D as disclosed, for example, in the aforementioned Patent No. 2,589,242. The circuits are also illustrated for registering car calls on electronic tubes. For convenience, but a seven floor installation is illustrated in which the first and second floors are lobbies. The floors are spaced equidistant apart. With such arrangement up landing call registering tubes U are provided for floors 1 to 6 inclusive, down landing call registering tubes D are provided for floors 2 to 7 inclusive. Also, top compartment car call registering tubes TC are illustrated for floors 1 to 7 inclusive, and bottom compartment car call registering tubes BC for floors 1 to 7 inclusive. For certain installations, as will be explained later, the top compartment first floor and bottom compartment seventh floor call registering tubes would not be provided. These tubes are cold cathode gas tubes which are broken down by the touch of a button BUT connected adjacent the anode to the envelope of the tube. A tube upon being broken down remains conductive, placing the potential across its load resistor RL on the corresponding selector call pickup contact. For example, upon tube U6 being caused to conduct to register an up sixth floor landing call, it places potential on the call pickup contact UH6. Also potential is applied by way of rectifier YU6 to stack circuit URSC controlling the coil of highest landing call switch HHD. Similarly for example, upon tube TC7 being caused to conduct to register a top compartment seventh floor car call, it places potential on top compartment call pickup contact TCP. Also potential is applied by way of rectifier YTC7 to the hook switch stack circuit HCSC controlling the coil of highest car call switch HCC.

When a call is answered, it is automatically cancelled, as will be explained later.

Knife switch K48 has three positions. In the upper position the motor generator set is shut down. In the middle position, the coil of motor generator switch MG is energized so as manually to start the motor generator set in operation. In the lower position the motor generator set is automatically started in operation. In describing the operation of the system, it will be assumed that knife switch K48 is in its lower position and that all other knife switches are open. It will also be assumed that the car is standing with the compartments at the lobbies (landings 1 and 2) and that the system is under night service operation so that night service switch VN is operated and thus contacts VN3 are separated and contacts VN1, VN2, VN4, VN5, VN6, VN7, VN8 and VN9 are engaged. With the compartments positioned at the lobbies, main landing switch ML is operated so that contacts ML2 and ML4 are separated. With contacts ML2 separated, the coil of motor generator switch MG is deenergized and the motor generator set is shut down. Contacts MG4 prevent condenser C15 being in a charged state and thus prevent operation of switch MG due to condenser discharge when switch K48 is moved to its lower position. Under the conditions assumed the doors for both compartments are closed. Also, with both compartments at the lobbies, brush RB on the selector synchronous panel is in engagement with contact MLC1, completing a circuit through contacts H1 for the coil of up operation switch OU. Thus switch OU is operated and its contacts OU2 are separated, de-energizing the coil of down operation switch OD. Also, contacts OU6 are in engagement, completing a circuit through contacts ALT1 and HNLS1, selector contact HZC2 and brush UHZB for the coil of landing call advanced zone switch HAZ, and contacts OU7 are in engagement, completing a circuit through contacts ALT2 and CNLS1, selector contact CZC2 and brush UCZB for the coil of car call advanced zone switch CAZ. Thus switches HAZ and CAZ are in operated condition. Also landing call zone switch HZ and car call zone switch CZ are in operated condition, the circuits for their coils being through selector contact HZC1 and brush HZB and through selector contact CZC1 and brush CZB respectively. For convenience, it is pointed out here that switches HZ and CZ are operated at each floor, in advance of the picking up of a call for that floor, to engage contacts HZ2 and HZ3 and contacts CZ2 and CZ3 respectively to enable the call to be picked up. Also contacts OU1 are in engagement, completing a circuit for the coil of direction control switch UD. Thus, switch UD also is in operated condition.

Assume now that an up landing call is registered say at the fourth floor. This is effected by causing conduction of tube U4 by touch. Upon the intending passenger touching the button BUT connected to the tube envelope, a circuit is established from ground GR through the secondary of transformer TF to line B which is connected through line B+ to the anode of the tube and thence from the button by way of the body of the intending passenger back to ground GR. As a result, sufficient alternating voltage is applied between the anode and tube envelope to break down the tube. When the tube becomes conductive it provides sufficient illumination to indicate that the landing call is registered. The registration of the call causes operation of highest landing call switch HUD. The circuit for the coil of switch HUD is from the left-hand side of load resistor RLU4 by way of rectifier YU4 to junction JU4, downwardly through rectifier stack circuits URSC to contact UHH1, brush BUHB, contacts BCO2, rectifier YHUD3, coil HUD, supply line B to the right-hand side of resistor RLU4. Switch HUD operates, engaging contacts HUD3 to complete a circuit through contacts BOT2, TOT1 and VN8 for the coil

of start switch SB. Switch SB operates to engage contacts SB6, completing a circuit through contacts ADV7 for the cooperating coil of stop magnet SM, effecting the retraction of the pawls. Switch HUD also engages contacts HUD2 to complete a circuit through contacts VN4 and switch K48 for the coil of motor generator switch MG. Switch MG operates to cause the starting of the motor generator set. It also engages contacts MG2 to complete a circuit for the coil of potential switch P. Thus as the motor generator set comes up to speed and the exciter voltage rises to a certain value, switch P operates to engage contacts P1. This completes a circuit through compartment door contacts TGC and BGC, contacts ST1 and contacts SB3 for the coil of preparatory to run switch GO. Switch GO operates, engaging contacts GO1 to establish a self holding circuit. It also engages contacts GO7 to prepare the circuit for generator field winding GMF through accelerating resistor GFAR. It also separates contacts GO8 to disconnect retardation resistor GFRR from the generator field winding. In addition, it engages contacts GO2 to complete a circuit for the armature AM and field winding AMF of the selector advance motor. The circuit through the armature, since switch UD is operated, is through contacts UD3 and UD6 so that the advance motor acts to advance the advance panel in the up direction and to close selector switches 1SCC to 5SCC in sequence.

The closing of selector switch 1SCC completes a circuit through compartment door contacts TGC, BGC and hoistway door contacts DS for the coil of field and brake switch H. Switch H operates to separate contacts H1 but switch OU is maintained operated by way of contact UD1. Switch H also separates contacts H17, disconnecting the generator field winding GMF from across the generator armature GA. At the same time, it engages contacts H15 to complete a circuit for the brake release coil BR and a circuit for the generator field winding GMF. The circuit for the generator field winding is through contacts H15 and GO7, resistor GFAR and contacts UD9 and UD12. The energization of the brake release coil causes the release of the electromechanical brake and as the generator field winding GMF is energized, the car is started. Since the circuit for the field winding is through contacts UD9 and UD12, the direction in which the car is started is up. As the compartments move away from the lobbies, switch ML drops out engaging contacts ML2 to maintain switch MG in operated condition.

The closing of selector switch 2SCC completes a circuit for the coil of advanced brush switch ADV. This switch engages contacts ADV1 to complete through contacts UD2 a holding circuit for switch UD. It also separates contacts ADV7 in the circuit for the operating coil of stopping magnet SM, this magnet acting however to retain the pawls in retracted position by residual magnetism. It also engages contacts ADV6 and ADV13 to complete a circuit for the coils of top compartment initial time switch TOT and bottom compartment initial time switch BOT respectively. These switches operate to separate contacts BOT2 and TOT1, breaking the circuit for the coil of switch SB. Switch SB releases, separating contacts SB3, but switch GO is maintained operated by its holding circuit.

Switch H upon operation also engages contacts H11 which with the closing of selector switch 3SCC completes a circuit for the coil of first speed switch 1SP and in parallel therewith through contacts 1SP3 for capacitor C1. Due to the delay imposed by the charging of capacitor C1, switch 1SP does not operate immediately. Upon operation it engages contacts 1SP6 to short circuit a portion of resistor GFAR to effect an increase in generator excitation and thus the speed of the hoisting motor. Switch 1SP also separates contacts 1SP3 to disconnect capacitor C1 from across the coil of the switch and engages contacts 1SP2 to effect the discharge of capacitor

C1. It also engages contacts 1SP4 to complete through contacts H11 and selector switch 4SCC a circuit for the coil of second speed switch 2SP and its parallel capacitor C2. Upon the charging of capacitor C2, switch 2SP operates to engage contacts 2SP4, short circuiting another step of resistor GFAR. This further increases the generator excitation and thus the speed of the hoisting motor. Switch 2SP also separates contacts 2SP2 to disconnect capacitor C2 from across the coil of the switch and engages contacts 2SP1 to discharge the capacitor. It also engages contacts 2SP3 to complete through contacts H11 and selector switch 5SCC, a circuit for the coil of third speed switch 3SP and its parallel capacitor C3. Upon the charging of capacitor C3, switch 3SP operates to engage contacts 3SP3, short circuiting the remaining step of resistor GFAR. This again increases the generator excitation to bring the hoisting motor up to full speed. It also separates contacts 3SP2 to disconnect capacitor C3 from across the coil of the switch, and engages contacts 3SP1 to effect the discharge of the capacitor.

The call pickup brushes may engage a live contact representing a call, either during the advance of the advancer panel or with the panel in advanced position, depending upon the amount of the advance, in turn dependent upon the speed of the installation, and the distance away of the landing at which the call is registered. Under the example of operation chosen, upon the engagement of brush TLUAB with stationary contacts UH4, a circuit is completed for landing call controlled coil of advance coil switch ACS from the left-hand side of resistor RLU4 by way of contacts OU11 and HAZ1 and line B to the right-hand side of the resistor. Switch ACS operates but the operation is without effect under the assumed conditions. Upon the engagement of brush TUB with contact UH4, a circuit is not completed for the coil of auxiliary top compartment landing call pickup switch XTHS as contacts BCO3 and GO3 are separated. However, upon the engagement of brush BUB with contact UH4, a circuit is completed across resistor RLU4 through contacts OU12, ADV12, BLS6, BCO4 and HZ3 and rectifier YXBHS2 for the coil of auxiliary bottom compartment landing call pickup switch XBHS. This switch operates to engage contacts XBHS1, completing a circuit for the coil of bottom compartment landing call pickup switch BHS. Switch BHS operates to engage contacts BHS3, completing a self holding circuit through contacts H12 and ADV5. It also engages contacts BHS2 to complete a circuit for the coil of stop switch ST. It also engages contacts BHS5 which prepares the cancellation circuit for the up fourth floor call.

Switch ST operates to engage contacts ST2 to complete a circuit through contacts ADV8 for the reset coil of stopping magnet SM which acts to neutralize the residual magnetism of the operating coil, releasing the pawls for engagement of the up pawl with the fourth floor stopping lug for bringing the car to a stop with the bottom compartment at the fourth floor. Switch ST also separates contacts ST1 to break the circuit for the coil of switch GO which releases, separating contacts GO2 to break the circuit for the advancer motor. It also engages contacts GO2 to maintain switch HDS operated. It also separates contacts GO7 and engages contacts GO8 to render accelerating resistor GFAR ineffective and retardation resistor GFRR effective for the slowdown operation. Switch GO also engages contacts GO9 which completes a circuit from the tapped point of the secondary winding of transformer TF through rectifier VTF by way of line AC1 through contacts XBHS2, BHS5 and ADV17, rectifier YXBHS1, contacts HZ3, BCO4, BLS6, ADV12 and OU12, brush BUB and contact UH4 to the cathode of tube U4. Rectifier YTF passes the positive halves of the alternating current cycle, raising the cathode potential sufficiently to pulse out the tube. Thus the call is automatically canceled as it is picked up. Switch XBHS releases with the canceling of the call.

As the bottom compartment arrives within a certain distance of the fourth floor, selector switch 5SCC is opened to break the circuit for the coil of switch 3SP. This switch releases to separate contacts 3SP4, inserting a portion of resistor GFRR in circuit with generator field winding GMF, reducing the generator excitation and thus the speed of the hoisting motor. As the bottom compartment arrives at a point closer to the fourth floor, selector switch 4SCC opens to break the circuit for the coil of switch 2SP. This switch releases to separate contacts 2SP5, inserting a further portion of resistor GFRR in circuit with the generator field winding and thus further reducing the speed of the hoisting motor. Similarly, as the bottom compartment arrives at a point still closer to the fourth floor, selector switch 3SCC opens, breaking the circuit for the coil of switch 1SP. This switch releases to separate contacts 1SP7, inserting the remainder of resistor GFRR in the generator field winding circuit, further reducing the speed of the motor. Just before the bottom compartment reaches the landing, selector switch 2SCC opens to break the circuit for the coil of switch ADV. Immediately after selector switch 2SCC opens, selector switch 1SCC opens to break the circuit for the coil of switch H. Switch H releases to separate contacts H15, breaking the circuit for the generator field winding GMF and for the brake release coil BR, with the result that the generator excitation is discontinued and the brake is applied to bring the compartment to a stop at the landing. Also contacts H17 engage to contact the generator field winding across the generator armature with a polarity to oppose the generator residual flux.

The advancer motor being deenergized as a result of the separation of contacts GO2 is returned to neutral position along with the opening of the selector switches. The circuit for the coil of switch HDS is maintained by way of switch HHC as brushes TUHB and BUHB move upwardly and are off the stationary contacts. Also this circuit is maintained by way of brush BUHB on contact UHH4 while the compartment is stopped at the fourth floor. This maintains the car set for up direction of travel.

When switch BHS is operated upon picking up the up fourth floor call, its contacts BHS1 engage to complete a circuit through contacts SB4 and VN2 and rectifier YBDTS for the coil of bottom compartment door time switch BDTS, causing this switch to operate. The resultant engagement of contacts BDTS3 completes a circuit through contacts MG6, BLS4 and OU9, selector brush BULB and contact ULC4 for the up hall lantern UHL4 for the fourth floor. This advises the intending passenger that a stop is to be made so that he may position himself in front of the door.

As the bottom compartment arrives at a certain distance from the fourth floor in the stopping operation, door zone switch DZ1 closes so that, with the re-engagement of contacts 1SP1, a circuit is completed through contacts BDTS1 for the coil of bottom compartment door open switch BDO. This switch operates to separate contacts BDO6 and BDO7 and engage contacts BDO5 and BDO8. This causes current to be supplied to the armature BDMA of the bottom compartment door operating motor in a direction to cause operation of the motor to open the bottom compartment door BCD and the fourth floor hoistway door HD. Thus the doors are moved to open position as the stop is made.

Upon the separation of contacts ADV5 and H12 as the stop is made, the coil of switch BHS is disconnected from the supply lines. Switch BHS releases to separate contacts BHS1, disconnecting the coil of switch BDTS from the supply lines. This switch does not release immediately, being delayed by the discharge of capacitor C13. Also, upon the separation of contacts ADV6 and H13 and the separation of contacts ADV13 and H16 as the stop is made, the coils of switches TOT and BOT respectively are disconnected from the supply lines.

These switches do not release immediately, being delayed in the case of switch BOT by the discharge of capacitor C7, and also of capacitor C8 connected across the coil by contacts BH5, to provide a greater delay since a landing call stop is involved and being delayed in the case of switch TOT by the discharge of capacitor C5, switch TOT not having the greater delay because contacts THS4 are not engaged and thus capacitor C6 is not effective. Switch SB is maintained in released condition until switches TOT and BOT release to engage contacts TOT1 and BOT2.

Assume that the intending passenger enters the bottom compartment and, wishing to be carried say to the fifth floor, registers a car call on tube BC5. This renders selector contact BCP5 alive and causes operation of highest car call switch HCC. This switch is operated by the potential drop across load resistor RLBC5 for tube BC5, the circuit for its coil being from the right-hand side of the resistor through rectifier YBC5, hook switches HC5-6, HC6-7 and HC7, the coil, to the left-hand side of the resistor. Switch HCC operates to separate contacts HCC1 in the circuit for the coil of up to down reversal switch UFR.

Upon the release of switches TOT and BOT at the expiration of their time intervals, contacts TOT1 and BOT2 engage to complete through contacts VN8 and ML4 a circuit for the coil of switch SB. Switch SB operates as previously described to effect reaction of the pawls.

With the separation of contacts BDTS1 upon the release of switch BDTS, switch BDO releases to separate contacts BDO5 and BDO8 and to engage contacts BDO6 and BDO7 to cause current to be supplied to the armature BDMA of the bottom compartment door operating motor to cause the closing of the doors. After switch BDTS releases to separate contacts BDTS3, the circuit for lantern is maintained through bottom compartment door close limit switch BDCL3 until the doors reach closed position. Should protective device contacts BDPD close as a result of the passenger transfer being effected during the closing operation, another circuit is completed for the coil of switch BDO to cause reopening of the doors. In that event the doors again close as the condition is overcome.

As the doors reach closed position, bottom compartment door contacts BGC and contacts DS for the fourth floor hoistway door close. The closing of contacts BGC completes a circuit through contacts ST1 and SB3 for the coil of switch GO. This switch operates to engage contacts GO2 to complete a circuit for the advancer motor field winding and through contacts UD3 and UD6 for the advancer motor armature to advance again the advancer panel for upward car movement. Upon the resultant closing of switch 1SCC, the circuit for the coil of switch H is again completed. Switch H operates to start the car in the up direction as above described. Upon the closing of switch 2SCC, switch ADV operates to separate contacts ADV8' which with the prior separation of contacts GO2' breaks the circuit for the coil of switch HUD. However, the resultant engagement of contacts HUD1 does not complete the circuit for the coil of switch UFR which is open at contacts HCC1.

Upon the engagement of brush BCUAB with contact BCP5, a circuit is completed by way of contacts OU13 and CAZ1 for the car call controlled coil of switch ACS, similar to the circuit traced for the coil of this switch in the landing call circuits. Again, the operation of switch ACS is without effect under the assumed condition.

Before brush BCB engages contacts BCP5 to pick up the bottom compartment fifth floor car call, cam CHC opens hook switch HC5-6. As there is no higher car call in either compartment under the conditions assumed, this breaks the circuit for the coil of switch HCC. Switch HCC releases, reengaging contacts HCC1 to complete through contacts VD1, HUD1 and UD7 a circuit for the coil of switch UFR. Switch UFR operates to engage

contacts UFR3 to complete a circuit for the coil of switch ST. Switch ST operates as previously described to cause the car to be slowed down and brought to a stop with the bottom compartment at the fifth floor. Switch UFR also separates contacts UFR1 to break the circuit for the coil of switch OU. Switch OU releases to cause the engagement of contacts OU2, completing a circuit for the coil of switch OD. Switch OD operates to engage contacts OD4, preparing a circuit for brush BDLB, contacts OU9 separating to render brush BULB ineffective.

Upon the engagement of brush BCB with contact BCP5, a circuit is completed for the coil of bottom compartment car call pickup switch BCS from the right-hand side of resistor RLBC5 through the contact and brush, contacts CZ3, the coil, and line B to the left-hand side of the resistor. Switch BCS operates to engage contacts BCS3 in a circuit for pulsing out tube BC5. This operation is not effected at this time, however, as contacts ADV15 are separated. Switch BCS also engages contacts BCS1 to complete a circuit for the coil of switch BDTS which operates to engage contact BDTS3, completing a circuit through contacts MG6, BLS4 and OD4, brush BDLB and contact DLC5 for the down hall lantern DHL5 for the fifth floor. It also engages contacts BDTS1 so that, as contacts 1SP1 engage and switch DZ1 closes as the bottom compartment arrives in the door zone for the fifth floor, a circuit is completed for the coil of switch BDO to cause the opening of the doors, enabling the passenger discharge to take place.

As selector switch 2SCC opens in the stopping operation to break the circuit for the coil of switch ADV, the release of switch ADV to re-engage contacts ADV15 completes a circuit through contacts BCS3 for pulsing out tube BC5 in the manner previously described. Thus, in the case of a car call stop, the call is not automatically canceled until the stopping operation is near completion. When the call is canceled, switch BCS releases.

Upon the release of switch BCS, it separates contacts BCS1 to disconnect to coil of switch BDTS from the supply lines, switch BDTS releasing after a time delay as above set forth to initiate the closing of the doors for the bottom compartment. When the stop is made, the release of switches H and ADV to separate contacts H3 and ADV1 breaks the circuit for the coil of switch UD which releases to set the car for downward travel. Also, upon the release of switches TOT and BOT, the coils of switches TOT and BOT are disconnected from the supply lines as previously described. Under the present assumed conditions, these switches are not delayed long in releasing as contacts THS4 and BH5 are separated because no landing call stop is involved. Thus current is supplied to their coils only by the discharge of condensers C5 and C7 respectively. Upon release, these switches re-engage contacts BOT2 and TOT1 to re-establish through contacts VN8 and ML4 the circuit for the coil of switch SB. SB operates as above described to effect release of the pawls.

As the doors reach closed position, the engagement of door contacts BGC and DS completes a circuit for the coil of switch GO. Thus upon the engagement of contacts GO2 upon the operation of switch GO, a circuit is completed for the armature AM of the advancer motor through contacts UD4 and UD5, causing the advance of the advancer panel in the down direction. Also, upon the operation of switch H in response to the closing of switch 1SCC as the advance takes place, a circuit is completed through contacts UD10 and UD11 for generator field winding GMF for reverse excitation. Thus the car in starting now travels in the down direction.

Assuming no further calls are registered, the car continues to the lower terminal where the compartments are brought to a stop at the lobbies (i.e., bottom compartment at the first floor and top compartment as the second floor).

The stop is initiated by the engagement of brush TSB on the advancer panel with lower terminal contact TC1. This completes a circuit through contacts ACS1 and ADV4 for the coil of switch ST, this switch operating to release the selector pawls as above described. Thus the down pawl engages the first floor stopping lug to cause the car to be slowed down and brought to a stop with the bottom compartment at the first floor. Inasmuch as no call is picked up, neither switch BDTS nor switch TDTS is operated so that no hall lantern is lighted and no doors are opened incident to the stopping operation. However, as a result of the engagement of brush RB with contact MLC1, upon the re-engagement of contacts H1 incident to the stopping operation, switch OU is operated and switch OD is released by the separation of contacts OU2. Switch UD is operated by the engagement of contacts OU1. Thus the car becomes set for upward travel. Also switch SB is not operated upon the re-engagement of contacts BOT2 and TOT1 as contacts ML4 are separated with the bottom compartment at the first floor. In addition, the separation of contacts ML2 breaks the circuit for the coil of switch MG which is delayed in releasing by the discharge of capacitor C15. If no further call is registered within a certain time interval, switch MG releases to shut down the motor generator set.

Assume that an intending passenger at the fourth floor registers a down call on tube D4 before the motor generator set shuts down. This causes operation of switch HUD, its coil being connected across load resistor RLD4 by way of stack circuit DRSC from junction point JD4, contact DHH2, brush TDHB and contacts TCO2. Switch HUD operates, engaging contacts HUD2 to re-establish the circuit for the coil of switch MG. It also engages contacts HUD3 which, if the time intervals of switches BOT and TOT have expired, completes a circuit by way of contacts BOT2, TOT1 and VN8 for the coil of switch SB. Switch SB causes operation of switch GO which in turn causes the advance of the advancer panel in the up direction. With the resultant closing of selector switch 1SCC, switch H is operated to cause the starting of the car which is thereafter brought up to full speed as previously described.

Upon the engagement of brush TDHB with stationary contact DHH4, the circuit for the coil of switch HUD is broken. This is because contact DHH4 is above junction point JD4 in the stack circuit, because the circuit via contact DHH3 and brush BDHB is open at contacts TCO3, because switch HHC is open, and because contacts GO2' and ADV8' are separated. Switch HUD releases to engage contacts HUD1, completing a circuit for the coil of switch UFR which in turn causes operation of switch ST. Switch ST operates as previously described to cause the car to be slowed down and brought to a stop. Inasmuch as under the assumed conditions switch HUD is released in response to the engagement of a top compartment brush with a fourth floor contact, the car is brought to a stop with the top compartment at the fourth floor landing.

Switch UFR, upon operation, also separates contacts UFR1 to break the circuit for the coil of switch OU. Switch OU releases, engaging contacts OU2 to cause operation of switch OD. Switch OD engages contacts OD6 to connect through contacts ADV11, TLS9, TCO5 and HZ2 the coil of switch XTHS across resistor RLD4. Switch XTHS engages contacts XTHS1 to cause operation of switch THS. Switch THS engages contacts THS3 to establish a self holding circuit. It also engages contacts THS5 which, along with the engagement of contacts GO9, completes a circuit through contacts XTHS2 and ADV16 to pulse out tube D4 and thus effect the automatic cancellation of the down landing call for the fourth floor, as previously described for canceling the up landing call at the fourth floor. Switch THS also engages contacts THS1 to complete through contacts SB1 and VN1 a cir-

cuit for the coil of switch TDTS. As a result, contacts TDTS3 engage to complete, through contacts MG5, TLS5, OD3 and ALR1 and brush TDLB and contact DLC4, a circuit for the fourth floor down hall lantern DHL4. Also contacts TDTS4 engage so that with the re-engagement of contacts 1SP5 in the slowdown operation and the arrival of the car in the door zone, the closing of door zone switch DZ2 completes a circuit for the coil of switch TDO. Switch TDO operates to separate contacts TDO4 and TDO5 and engage contacts TDO3 and TDO6, causing energization of the top compartment door motor armature TDMA. This motor operates to open the doors as the stop is made. Switch THS releases upon the separation of contacts ADV5 and H12 as the stop is made, separating contacts THS1 to break the circuit for the coil of switch TDTS. Also the coils of switches TOT and BOT are disconnected from the supply lines by the separation of contacts ADV6, H13, ADV13 and H16.

Assume that the intending passenger enters the top compartment and, wishing to be carried to the lobby, registers a car call for the second floor on tube TC2. Upon the expiration of the time delay due to discharge of capacitor C11, switch TDTS releases to initiate closing of the doors. Also upon the expiration of their time delays, switches TOT and BOT release to re-engage contacts BOT2 and TOT1 respectively, causing reoperation of switch SB. Switch SB, upon operation, causes release of the pawls, advance of the advancer panel and the starting of the car as the doors reach closed position as above described. As switch UD is released as a result of the separation of contacts ADV1 and H3 in the stopping operation, the advancer panel is advanced and the car is started in the down direction.

Upon the engagement of brush TCB with stationary contact TCP2, a circuit is completed through contacts CZ2 for the coil of switch TCS. Switch TCS operates to engage contacts TCS2, completing a circuit for the coil of switch ST. Switch ST operates as above described to cause the car to be slowed down and brought to a stop with the top compartment at its lobby. Upon the engagement of contacts ADV14 incident to the stopping operation, a circuit is completed by way of contacts TCS3 for pulsing out tube TC2. Switch TCS also engages contacts TCS1 to complete a circuit through contacts SB1 and H2 for the coil of switch TDTS. Switch TDTS operates to engage contacts TDTS4 to cause operation of switch TDO to effect the opening of the doors as the car comes to a stop. Switch TDO also engages contacts TDO7 to complete a self holding circuit through contacts SB7, MG7 and ML6, the last mentioned contacts now being in engagement because the car is at the lower terminal. Also, upon the re-engagement of contacts H1 as the car comes to a stop, switch OU is operated to set the car for upward travel as above described. Also, it engages contacts OU8 to complete a circuit through contacts MG5, TLS5 and TDTS3, brush TULB and contact ULC2, and contacts VN7 for the up hall lantern UHL2 for the second floor. If on further calls are registered, the car parks at the lobbies and, upon expiration of its time interval, switch MG releases to shut down the motor generator set. The resultant separation of contacts MG5 extinguishes the hall lantern. Also the separation of contacts MG7 breaks the holding circuit for the coil of switch TDO which releases to cause closing of the doors, it being assumed to aid in the simplification of circuits that there is sufficient energy in the motor generator set during shutdown to effect this operation.

Assume now that an intending passenger, say at the first floor, wishes to be carried in the up direction. He touches the button connected to tube U1, causing conduction of the tube to take place. This completes a circuit by way of contact UH1, brush BUB and contacts OU12 and GO5, for the coil of switch XBHS. This switch operates to cause operation of switch BHS, which in turn causes operation of switch BDTS. Switch BDTS engages contacts BDTS2 to complete a circuit for the

coil of switch MG and also engages contacts BDTS1 to cause operation of switch BDO. Switch MG causes starting of the motor generator set and engages contacts MG6 to complete, through contacts BLS4, BDTS3 and OU9, brush BULB and contact ULC1 and contacts VN9, a circuit for the up hall lantern UHL1 at the first floor. Switch BDO engages contacts BDO9 bypassing contacts ADV17 to cause the pulsing out of tube U1. Thus switches XBHS and BHS release. Switch BDTS is maintained operated by the discharge of capacitor C13 after the separation of contacts BHS1. Switch BDO also engages contacts BDO1 to complete through contacts SB2, MG1 and ML1 a self holding circuit. Switch BDO also separates contacts BDO6 and BDO7 and engages contacts BDO5 and BDO8. Thus upon the operation of switch P to engage contacts P1 as the motor generator set comes up to speed, a circuit is completed for the bottom compartment door operating motor to open the doors. Had the button for tube U2 for the second floor been touched instead of button U1, switch TDTS is operated, engaging contacts TDTS2 to cause the starting of the motor generator set and also engaging contacts TDTS4 to cause operation of switch TDO to effect the opening of the doors for the top compartment. Switch TDO also engages contacts TDO8 to effect the pulsing out of tube U2. Contacts GO3, GO4, GO5 and GO6 act to prevent the picking up of the call when a button is touched as the car is leaving the floor.

Assume that the intending passenger enters the bottom compartment and registers a sixth floor car call on tube BC6. This causes operation of switch HCC which engages contacts HCC2 to bypass contacts BDTS2 in the circuit for the coil of switch MG. It also engages contacts HCC3 to complete a circuit for the coil of switch SB. Switch SB operates, separating contacts SB2 to break the holding circuit for the coil of switch BDO. Thus, upon the expiration of the time interval of switch BDTS, the separation of contacts BDTS1 breaks the circuit for the coil of switch BDO which releases to cause reclosing of the doors. As the doors reach closed position, the closing of door contacts BGC completes through contacts SB3 a circuit for the coil of switch GO. Switch GO acts to cause advance of the advancer panel and, with the operation of switch H, the car is started in the up direction. Upon the engagement of cam CHC with hook switch HC6-7, circuits are set up as above described to cause the car to be brought to a stop with the bottom compartment at the sixth floor.

As a résumé of the operation so far described, during the upward travel of the car, stops are made in response to up landing calls by the bottom compartment. These stops are made in the order in which the floors are reached, being initiated in each case by the engagement of brush BUB with the stationary contacts for the floors for which the up calls are registered. Also stops are made in response to car calls for the bottom compartment, being initiated by the engagement of brush BCB with its stationary contacts for the floors for which bottom compartment car calls are registered. The operation of switch ST under such conditions is effected by the engagement of contacts BCS2. In case car calls are registered in the top compartment, say by entering passengers at the upper lobby, stops are made in response to such calls, being initiated by the engagement of brush TCB with its stationary contacts for the floors for which top compartment car calls are registered. In case the highest landing call is a down call, it is answered by the top compartment as previously described for a fourth floor down call and that car is set for downward travel as the stop is made. In case the highest call is a car call, again the car is set for downward travel as the stop is made. This has been previously described with reference to a bottom compartment fifth floor car call. The same result is had in case the highest car call is a top compartment call.

During downward travel of the car, down landing calls are answered by the top compartment. These stops are made in the order in which the floors are reached, being initiated in each case by the engagement of brush TDB with the stationary contacts for the floors for which down calls are registered and the call pickup circuit for the coil of switch XTHS extending through contacts OD6 and ADV9. The operation of switch ST under such conditions is effected by the engagement of contacts THS2. Also the top compartment stops for its car calls during the downward trip, the calls being picked up by the engagement of brush TCB with contacts TCP for the floors for which such calls are registered. It is possible for the bottom compartment to have registered car calls on the downward trip as will be seen as the description proceeds. Under such conditions the bottom compartment is stopped at the floors for which such calls are registered, the calls being picked up by the engagement of brush BCB with contacts BCP for the floors for which such calls are registered.

When the bottom compartment picks up an up landing call or bottom compartment car call on its upward trip, under conditions where an up landing call is in registration for the floor next above, the top compartment responds to such call above. Similarly, when the top compartment picks up a down landing call or top compartment car call on its downward trip under conditions where a down landing call is in registration for the floor next below, the bottom compartment responds to such call below. Inasmuch as this condition is more likely to arise during daytime, an explanation of this operation will be deferred until such daytime operation is being discussed.

Before discussing daytime operation of the system, it is to be noted that it may be considered desirable, especially under night service conditions, to have one compartment provide all the service. To have the bottom compartment provide this service, knife switch K33 is moved into its lower position, completing a circuit through contacts VN6 for the coil of top compartment out of service switch TCO. This switch operates to take the top compartment out of service. In so doing it separates contacts TCO5 to prevent the top compartment picking up landing calls, separates contacts TCO2 and engages contacts TCO3 to render top compartment brush TDHB ineffective and bottom compartment brush BDHB effective in the down landing call above circuit DRSC, engages contacts TCO1 to render the up landing call for the second floor effective in the up landing call above circuit URSC, and engages contacts TCO4 to render the bottom compartment subject to all landing calls. Also, knife switch K57 is closed to render the bottom compartment top floor car call registering tube BC7 effective to register calls. To have the top compartment provide all the service, knife switch K33 is moved into its upper position, completing a circuit through contacts VN5 for the coil of bottom compartment out of service switch BCO. This switch operates to take the bottom compartment out of service. In so doing it separates contacts BCO4 to prevent the bottom compartment picking up landing calls, separates contacts BCO2 and engages contacts BCO1 to render bottom compartment brush BUHB ineffective and top compartment brush TUHB effective in the up landing call above circuit URSC, and engages contacts BCO3 to render the top compartment subject to all landing calls. Also, knife switch K58 is closed to render the top compartment lower lobby car call registering tube TC1 effective to register calls and preferably also knife switch K49 is closed to enable, when the top compartment is parked at the upper lobby, the top compartment doors to be opened in response to the registering of the down landing call for that floor, as will be seen from later description.

elevators is to handle heavy traffic. This condition is most prevalent during daytime operation, traffic under night service conditions being relatively light. However, it is believed that the above described operations under night service conditions will be of considerable assistance in an understanding of the operation under heavier traffic conditions. Systems have been proposed for automatically switching over in response to service demand from night service operation to daytime operation during which the cars are timed dispatched from one or both terminals. Such arrangement has not been here shown but for convenience it will be assumed that such change is made by causing the release of switch VN, either in response to service demand or manually.

When switch VN releases, it separates contacts VN4 and engages contacts VN3 to render the coil of switch MG subject to contacts WB1 of the switch for selecting the car for dispatching from the lobbies. Thus, say the change is effected manually, upon operation of switch WB, switch MG is operated to become self holding at contacts MG3 and to start the motor generator set. If the change is effected automatically, contacts MG3 maintain switch MG in operated condition. Also switch VN separates contacts VN8 to render the circuit for the coil of switch SB subject at the terminals to contacts DIS1 of dispatch switch DIS. Also it separates contacts VN7 and VN9 to render lighting of the hall lanterns at the lobbies subject to selection of the car for dispatching.

It will be assumed that the switchover is effected automatically, that the compartments are at the lobbies and that the motor generator set is in operation at the time. Under such conditions, the doors for the compartments may be open or closed, depending for each compartment upon whether a passenger transfer was involved. If a compartment's doors are open at this time, they are maintained open by the holding circuit for the coil of the door open switch for that compartment. In case of the bottom compartment for example, the holding circuit for the coil of switch BDO when the compartments are stopped at the lobbies is through contacts SB2, MG1, ML1, BDO1 and 1SP1 and switch DZ1.

Upon selection of the car for dispatching, switch WB is operated, engaging contacts WB2 and WB3, which cause the lighting of up hall lanterns UHL2 and UHL1 for the top and bottom compartments, respectively, if in each case the doors for that compartment are open. Upon expiration of the up dispatch time interval, the dispatching operation is initiated and, incident to the dispatching, switch WBX is operated to engage contacts WBX1, completing a circuit for the coil of dispatch switch DIS. Switch DIS operates to engage contacts DIS1, completing a circuit for the coil of switch SB. Switch SB operates to separate contacts SB2 and SB7. This breaks the holding circuit for the coil of the door open switch for each compartment whose doors are open, initiating their closing. Switch SB also engages contacts SB3 to effect the starting of the car in the up direction as the doors reach closed positions as previously described. It is to be understood that under certain traffic conditions, the cars may be time dispatched on their downward trips. This is illustrated as effected by completing the circuit for the coil of switch DIS by contacts WTS1 of top terminal starting switch WTS, operated incident to a down dispatch operation initiated by the expiration of the down dispatch time interval. At the top floors the holding circuits for the coils of the door open switches are through contacts THL1 and THL2, bypassing contacts ML1 and ML6 respectively.

On a trip to the top terminal, stopping of the car is assured as a result of the engagement of brush TSB with stationary contact TC6, which completes a circuit through contacts ACS1 and ADV4 for the coil of switch ST. Also the setting of the car for downward travel at the top terminal is assured as a result of the engage-

ment of brush UTRB with stationary contact UTRC6, which as the car comes to a stop completes a circuit through contacts H10, HCC1, HUD1 and UD7 for the coil of switch UFR, contacts VD1 being separated when the car is subject to down timed dispatching. Switch UFR operates to separate contacts UFR1 which causes the car to be set for downward travel as previously explained.

Under up peak conditions, the car may reverse at its highest call as described under night service conditions, contacts VD1 of the down traffic switch being in engagement under up peak conditions. Contacts VT1 and VT2 enable circuits to be completed for the down hall lanterns DHL7 and DHL6 at the top floor and the next to the top floor when the system is operating under night service conditions as switch VT is not operated under such conditions. Contacts VT1 in conjunction with contacts WT1 and contacts VT2 in conjunction with contacts WT2 enable circuits to be completed for down hall lanterns DHL6 and DHL7 when the system is operating under up peak conditions. Also the car may be reversed under conditions where it is subject to timed dispatching on its downward trip when it is late in arriving at the upper terminal, provided it has reached its highest call. Upon the engagement of contacts WTX1, incident to the down dispatching operation, a circuit is completed for the coil of down dispatch switch DDS. This switch operates to engage contacts DDS1 which, if the car has reached its highest call so that contacts HCC1 and HUD1 are engaged, completes a circuit for the coil of switch UFR to effect the reversal operation, contacts VD1 being separated when the car is subject to down timed dispatching as pointed out above.

As under night service conditions, on an upward trip the bottom compartment responds to up landing calls. The circuit for the coil of switch BDTS when such stops are made is by way of contacts ADV3, bypassing contacts VN2. Also, on a downward trip, the top compartment responds to down landing calls. The circuit for the coil of switch TDTS when such stops are made is by way of contacts ADV2, bypassing contacts VN1. Both compartments also stop in response to their car calls on both the upward trip and the downward trip. The top compartment responds to a down call on the upward trip if such call is the highest call under up peak traffic conditions or late car conditions during down dispatching. When a call is picked up, the hall lantern is lighted for the floor for which the call is registered and for the direction in which the car will leave that floor. Also the doors for the compartment which stops at that floor are opened as the stop is made.

When a stop is initiated in response to the bottom compartment picking up a call for an intermediate floor on its upward trip, the conditions may be such that an up landing call is in registration for the floor next above the one at which the stop is being made. Under such conditions, as soon as switch ST is operated incident to initiating the stopping operation, the separation of its contacts ST1 breaks the circuit for the coil of switch GO. Switch GO releases to engage contacts GO3. Thus a circuit is completed which connects the coil of switch XTHS across load resistor RL for the tube registering such floor next above up landing call, say resistor RLU4. Thus switch XTHS is operated to cause operation of switch THS which in turn becomes self held and engages contacts THS5 to cause the pulsing out of the call. Also, it engages contacts THS1 to cause operation of switch TDTS which engages contacts TDTS3 to cause the lighting of the up hall lantern for such next above floor. It also engages contacts TDTS4 so that, as the car arrives at the floors, a circuit is completed for the coil of switch TDO to cause the opening of the top compartment doors. Thus the intending passenger may enter the top compartment and register a car call for his destination. Upon expiration of the time delays of switches

BDTS and TDTS, the doors of both compartments close and, with the expiration of the time delays of switches BOT and TOT, the car is restarted in the up direction.

Similar operation is had for down car travel. When a stop is initiated in response to the top compartment picking up a call for an intermediate floor under conditions where a down landing call is in registration for the floor next below, the operation of switch ST breaks the circuit for the coil of switch GO. This switch releases to engage contacts GO6, thus completing a circuit connecting the coil of switch XBHS across load resistor RL for the tube registering such floor next below down landing call. Thus switch XBHS is operated to cause operation of switch BHS which in turn becomes self held and engages contacts BHS5 to cause pulsing out of the call. Also, it engages contacts BHS1 to cause operation of switch BDTS which engages contacts BDTS3 to cause the lighting of the down hall lantern for such next below floor. It also engages contacts BDTS1 so that, as the car arrives at the floors, a circuit is completed for the coil of switch BDO to cause the opening of the bottom compartment doors. Thus the intending passenger may enter the bottom compartment and register his car call. Upon the expiration of the passenger transfer time delays, the doors of both compartments close and the car is restarted in the down direction.

The condition may arise where for upward travel a top compartment car call is registered for the same floor for which an up landing call is registered. Under such conditions, upon the engagement of brush TCB with its stationary contact for such floor, switch TCS is operated, in turn to cause operation of switch ST and thus the release of switch GO. Switch GO engages contacts GO3, causing the operation of switch XTHS and thus the answering of both calls by the top compartment. Similarly, where for downward travel a bottom compartment car call is registered for the same floor for which a down landing call is registered, upon the engagement of brush BDB with the stationary contact for such floor, switch BCS is operated. As a result, switch ST is operated and switch GO is released to engage contacts GO5, causing the operation of switch XBHS and thus the answering of both calls by the bottom compartment.

Switch DIS is maintained operated between terminals by contacts WTS1. Thus contacts DIS1 are in engagement so that at stops at intermediate floors, switch SB is operated to initiate the restarting of the car upon expiration of the time intervals of switches TOT and BOT. If on a stop at a terminal a passenger transfer is not involved for either or both compartments, the doors of that compartment remain closed and the hall lantern for that compartment is not lighted. However, if an intending passenger at a lobby or at an upper terminal floor touches the landing call registering button at that floor, the doors for the compartment at that floor are opened and, provided the car is selected for dispatching, the hall lantern at that floor for the direction in which the car will leave is lighted. This has already been explained under night service operation for the lobbies. As to the upper terminal floors, selection of the cars for down dispatching involves the operation of switches WT. Thus if contacts WT1 and WT2 are engaged, the opening of the doors for either or both compartments to effect closure of door close limit switch TDCL3, BDCL3 for that compartment causes the lighting of the down hall lantern for the floor or floors involved. Once the doors are opened at the lobbies or upper terminal floors, they are maintained open by switch SB until the dispatching operation takes place.

Should the bottom compartment take on enough passengers to operate its load weighing switch BLW, a circuit is completed through contacts H5 for the coil of bottom compartment load switch BLS. This switch operates to engage contacts BLS3 preparing a self holding circuit which is completed by contacts H7 upon starting of the

car. It also separates contacts BLS6, to prevent the picking up of landing calls by the bottom compartment, and separates contacts BLS4 to prevent the lighting of hall lanterns at floors at which the bottom compartment stops. 5 Switch BLS is released when a stop is made in response to a bottom compartment car call under conditions where there is sufficient passenger discharge to permit the opening of switch BLW. A similar load operation is had when top compartment load switch TLW is operated to 10 complete a circuit through contacts H8 for the coil of switch TLS. This switch engages contacts TLS2 in a self holding circuit, completed by the engagement of contacts H9 incident to the starting of the car. It also separates contacts TLS9 to prevent picking up of landing calls 15 and contacts TLS5 to prevent lighting of hall lanterns at floors at which the top compartment stops. Switch TLS is released when room is again provided in the compartment to receive passengers when a top compartment car call stop is made.

20 Instead of the bottom compartment picking up up landing calls to initiate stopping operations on up trips and the top compartment picking up down landing calls to initiate stopping operations on down trips, as above described, the system may be arranged so that the top compartment picks up each up landing call to initiate stopping operations on up trips, except that the bottom compartment answers the call under conditions where a bottom compartment car call is in registration for the same floor, or an up landing call or top compartment car call 25 is in registration for the floor next above or the call is registered too late to be picked up by the top compartment but not too late to be picked up by the bottom compartment. Also the bottom compartment picks up each down landing call to initiate stopping operations on 30 down trips, except that the top compartment answers the call under conditions where a top compartment car call is in registration for the same floor, or a down landing call or bottom compartment car call is in registration for the floor next below, or the call is registered too late to 35 be picked up by the bottom compartment but not too late to be picked up by the top compartment. This is effected by closing knife switches K51 and K56.

Assume that with switches K51 and K56 closed, an up landing call is registered, for example, for the fourth floor. 45 With the car set for upward travel, upon the engagement of brush TUB with contact UH4, a circuit is completed by way of contacts OU10, ADV9 and ACS2, switch K51, and contacts TLS9, TCO5 and HZ2 for the coil of switch XTHS, picking up the call and thus causing 50 the car to be slowed down and brought to a stop with the top compartment at the fourth floor. Also the up fourth floor hall lantern UHL4 is lighted as the call is picked up and the doors are opened as the stop is made, as previously described, the circuit for the hall lantern 55 being through contacts TDTS3 and brush TULB and the circuit for the coil of switch TDO being through contacts TDTS4. Also, the call is automatically canceled as a result of the operation of switch THIS so that this call is not answered again by the bottom compartment after the 60 car is restarted in the up direction. In case the highest call is a down landing call, this call is answered by the top compartment in the manner previously described.

Assume now that the car is set for downward travel and that a down call is registered, say for the fourth floor. 65 Upon the engagement of brush BDB with contact DH4, a circuit is completed by way of contacts OD8, ADV10 and ACS3, switch K56 and contacts BLS6, BCO4 and HZ3 for the coil of switch XBHS. This picks up the call and thus causes the car to be slowed down and brought to a stop with the bottom compartment at the fourth floor. Also the down fourth floor hall lantern DHL4 is lighted as the call is picked up and the doors are opened as the stop is made, as previously described, the circuit for the hall lantern being through contacts 70 BDTS3 and the circuit for the coil of switch BDO being

through contacts BDTS1. Also, the call is reset as a result of the operation of switch BHS so that this call is not answered again by the top compartment.

During travel of the car in each direction, stops are made in response to car calls for each compartment, as has previously been explained.

Assume now a condition where for up car travel there is an up landing call at the fourth floor and an up landing call at the fifth floor. Upon the engagement of advance brush TLUAB with contact UH4, a circuit is completed for the landing call controlled coil of switch ACS, as previously pointed out. Switch ACS operates to separate contacts ACS2, but this is without effect. However, upon the engagement of brush TLUAB with contact UH5, the resultant separation of contacts ACS2 prevents the establishment of a circuit for the coil of switch XTHS upon the engagement of brush TUB with contact UH4. Thus the top compartment does not pick up the up fourth floor call under these conditions and a stop is not made by the top compartment at the fourth floor. Upon the engagement of brush TLUAB with contact UH6, switch ACS is not operated as there is no up landing call registered for the sixth floor. Thus upon the engagement of brush TUB with contacts UH5 a circuit is completed by way of contacts OU10, ADV9 and ACS2 and knife switch K51 for the coil of switch XTHS. At the same time a circuit is completed by the engagement of brush BUB with contact UH4 through contacts OU12 and ADV12 for the coil of switch XBHS. Switches XTHS and XBHS operate to cause the lighting of the up hall lanterns at the fifth and fourth floors, the automatic cancellation of the up landing calls for these floors, the slowing down of the car and bringing it to a stop with the top compartment at the fifth floor and bottom compartment at the fourth floor and the opening of the doors for both compartments as the car is brought to a stop.

A similar operation is had in the event that a car call in the top compartment is in registration for the floor next above the one for which an up landing call is in registration. For convenience, assume again that an up landing call is in registration for the fourth floor and that a top compartment car call is in registration for the fifth floor. Upon the engagement of brush TCUAB with contact TCP5, a circuit is completed through contacts OU13 and CAZ1 for the car call controlled coil of switch ACS. This switch operates to separate contacts ACS2 as before, preventing the top compartment picking up the up fourth floor landing call upon the engagement of brush TUB with contact UH4. Thus a call is not picked up to initiate the stopping of the car until brush TCB engages contact TCP5 and brush BUB engages contacts UH4. When this takes place, the circuits are completed for the coils of switches TCS and XBHS to cause the lighting of the hall lanterns for these floors, the automatic cancellation of the up fourth floor call, the slowing down and stopping of the car with the compartments at the fifth and fourth floors, the opening of the compartment doors as the car comes to a stop, and the automatic cancellation of the fifth floor top compartment car call.

A similar operation is had in the event that the bottom compartment has a car call for the floor for which the up landing call is registered. Assume again that an up landing call is in registration for the fourth floor and that in this case a bottom compartment car call is also in registration for the fourth floor. Upon the engagement of brush BCUAB with contact BCP4, a circuit is completed for the car call controlled coil of switch ACS which again separates contacts ACS2, preventing completion of a circuit for the coil of switch XTHS upon the engagement of brush TUB with contact UH4. However, upon engagement of brush BUB with contact UH4 and brush BCB with contact BCP4, circuits are completed to cause the operation of switches XBHS and BCS to cause the lighting of the up hall lantern at the fourth floor, the automatic cancella-

tion of the up fourth floor call, the slowing down of the car to bring it to a stop with the bottom compartment at the fourth floor, the opening of the bottom compartment doors and the automatic cancellation of the fourth floor bottom compartment car call.

Assume now a condition where an up landing call is in registration for each of three successive floors; for example, floors 4, 5 and 6. Under such conditions, the engagement of brush TLUAB with contact UH5 causes operation of switch ACS to prevent the picking up of the up fourth floor landing call by the engagement of brush TUB with contact UH4. Also, the engagement of brush TLUAB with contact UH6 again causes operation of switch ACS to prevent the picking up of the up fifth floor landing call upon the engagement of brush TUB with contact UH5. However, at the same time that brush TUB engages contact UH5, brush BUB engages contact UH4. Thus a circuit is completed by way of contacts OU12 and ADV12 for the coil of switch XBHS, picking up the up fourth floor call to initiate the slowing down of the car to bring the bottom compartment to rest at the fourth floor. Upon the release of switch GO incident to this operation, the engagement of contacts GO3 completes a circuit through contact UH5 and brush TUB for the coil of switch XTHS so that both the fourth and fifth floor calls are automatically canceled, the up hall lantern at the fifth floor as well as that at the fourth floor is lighted incident to the stopping operation and the doors for both compartments are opened as the car is brought to a stop. Upon the expiration of the passenger transfer interval, the car is restarted in the up direction and then brought to a stop with the top compartment at the sixth floor, the call being picked up upon the engagement of brush TUB with contact UH6. The up sixth floor hall lantern is lighted, the call is canceled and the top compartment doors are opened incident to the stopping operation.

Assume now a condition where up landing calls are in registration for four successive landings. Under such conditions two stops are made, the first being initiated in response to the engagement of brush BUB with contact UH for the lowest of such calls and the next in response to the engagement of brush BUB with contact UH for the next to the highest of such calls. In each case, the up hall lanterns are lighted for the floors at which the stops are being made, the up landing calls for such floors are canceled and the doors for both compartments are opened as the car comes to a stop.

Where the up landing call is registered too late to be picked up by the top compartment but in time to be picked up by the bottom compartment, upon the engagement of brush BUB with contact UH for the floor for which such late call is registered, a circuit is completed for the coil of switch XBHS. This picks up the call to initiate slowing down of the car to bring the bottom compartment to a stop at the floor for which such call is registered.

Similar operation is had for down car travel. Assume a condition where there is a down landing call at the fourth floor and a down landing call at the third floor. Upon the engagement of advance brush BLDAB with contact DH3, a circuit is completed by way of contacts OD7 for the landing call controlled coil of switch ACS, the circuit for the coil of switch HAZ for downward travel being through contacts OD9. Switch ACS operates to separate contacts ACS3, preventing the operation of switch XBHS upon the engagement of brush BDB with contact DH4. Thus the bottom compartment does not pick up the down fourth floor call. As switch ACS is not operated when brush BDB engages contacts DH3, a circuit is completed by way of contacts OD8, ADV10 and ACS3 and knife switch K56 for the coil of switch XBHS. At the same time a circuit is completed by the engagement of brush TDB with contact DH4 through contacts OD6 and ADV11 for the coil of switch XTHS. Switches XBHS and XTHS operate to cause the lighting of the down hall lanterns at the fourth

and third floors, the automatic cancellation of the calls, the slowing down of the car and bringing it to a stop at the fourth and third floors and the opening of the doors for both compartments as the car is brought to a stop.

A similar operation is had in the event that a car call in the bottom compartment is in registration for the floor next below the one for which a down landing call is in registration. For convenience, assume that a down landing call is in registration for the fourth floor and a bottom compartment car call is in registration for the third floor. Upon the engagement of brush BCDAB with contact BCP3, a circuit is completed through contacts OD11 and CAZ1 for the car call controlled coil of switch ACS, the circuit for the coil of switch CAZ for downward travel being through contacts OD10. This switch operates to separate contacts ACS3 as before, preventing the bottom compartment picking up the down fourth floor landing call upon the engagement of brush BDB with contact DH4. Thus a call is not picked up to initiate the stopping of the car until brush BCB engages contact BCP3 and brush TDB engages contacts DH4. When this takes place, the circuits are completed for the coils of switches BCS and XTHS to cause the lighting of the down hall lanterns for these floors, the automatic cancellation of the down fourth floor call, the slowing down and stopping of the car with the compartments at the fourth and third floors, the opening of the compartment doors as the car comes to a stop, and the automatic cancellation of the third floor car call.

A similar operation is had in the event that the top compartment has a car call for the floor for which the down landing call is registered. Assume again that a down landing call is in registration for the fourth floor and that in this case a top compartment car call is also in registration for the fourth floor. Upon the engagement of brush TCDAB with contact TCP4, a circuit is completed for the car call controlled coil of switch ACS which again separates contacts ACS3, preventing completion of a circuit for the coil of switch XBHS upon the engagement of brush BDB with contact DH4. However, upon engagement of brush TDB with contact DH4 and brush TCB with contact TCP4, circuits are completed to cause the operation of switches XTHS and TCS to cause the lighting of the down fourth floor hall lantern, the automatic cancellation of the down fourth floor landing call, the slowing down of the car to bring it to a stop with the top compartment at the fourth floor, the opening of the top compartment doors as the car is brought to a stop and the cancellation of the fourth floor top compartment car call.

Assume now a condition where a down landing call is in registration for each of three successive floors; for example, floors 5, 4 and 3. Under such conditions, the engagement of brush BLDAB with contact DH4 causes operation of switch ACS to prevent the picking up of the down fifth floor landing call by the engagement of brush BDB with contact DH5. Also, the engagement of brush BLDAB with contact DH3 again causes operation of switch ACS to prevent the picking up of the down fourth floor landing call upon the engagement of brush BDB with contact DH4. However, at the same time that brush BDB engages contact DH4, brush TDB engages contact DH5. Thus a circuit is completed by way of contacts OD6 and ADV11 for the coil of switch XTHS, picking up the down fifth floor call to initiate the slowing down of the car to bring the top compartment to rest at the fifth floor. Upon the release of switch GO incident to this operation, the engagement of contacts GO6 completes a circuit through contact DH4 and brush BDB for the coil of switch XBHS so that both the fifth and fourth floor calls are automatically canceled, the down hall lantern at the fourth floor as well as that at the fifth floor is lighted incident to the stopping operation and the doors for both compartments are opened as the car is brought to a stop. Upon the expiration

of the passenger transfer interval, the car is restarted in the downward direction and then brought to a stop with the bottom compartment at the third floor, the call being picked up upon the engagement of brush BDB with contact DH3. The down third floor hall lantern is lighted, the call is cancelled and the bottom compartment doors are opened incident to the stopping operation.

Assume now a condition where down landing calls are in registration for four successive landings. Under such conditions two stops are made, the first being initiated in response to the engagement of brush TDB with contact DH for the highest of such calls and the next in response to the engagement of brush TDB with contact DH for the next to the lowest of such calls. In each case, the down hall lanterns are lighted for the floors at which the stops are being made, the down landing calls for such floors are canceled and the doors for both compartments are opened as the car comes to a stop.

Where the down landing call is registered too late to be picked up by the bottom compartment but in time to be picked up by the top compartment, upon the engagement of brush TDB with contact DH for the floor for which such late call is registered, a circuit is completed for the coil of switch XTHS. This picks up the call to initiate slowing down of the car to bring the top compartment to a stop at the floor for which such call is registered.

It may be considered desirable for certain installations to have, during travel in a given direction, the leading compartment pick up the landing calls for that direction and, during travel in the other direction, the following compartment to pick up the landing calls for that direction. This may be effected by closing either switch K51 or K56, depending upon which direction it is desired to have the leading compartment pick up the calls. For example, by closing switch K51 while having switch K56 open, the top (leading) compartment would pick up the up landing calls on the up trip and the top (following) compartment would pick up the down landing calls on the down trip, subject to the exceptions previously discussed. The net result of this would be to have the top compartment bear the brunt of the service and this arrangement would be particularly suitable for example for installations in which the upper lobby is more accessible. By closing switch K56 while leaving switch K51 open, the bottom (following) compartment would pick up the up landing calls on the up trip and the bottom (leading) compartment would pick up the down landing calls on the down trip, subject to the exceptions previously discussed. The net result of this would be to have the bottom compartment bear the brunt of the service and this arrangement would be particularly suitable for example for installations in which the lower lobby is more accessible.

Under conditions where on an up trip a high call reversal operation is obtained, either under night service or up peak conditions, or under dispatching when a car is late in arriving at the top floors, the highest call if a down landing call or top compartment car call is answered by the top compartment, as previously set forth. It may happen under such conditions that a down landing call is also in registration for the floor next below the one for which such highest call is registered. Under such conditions, the bottom compartment answers the down landing call below, regardless of whether the system is arranged so that on the up trip the bottom compartment answers up landing calls or the top compartment answers such calls. In either case, when such highest call is picked up, switch UFR is operated, as a result of the engagement of contacts HCC1 or HUD1 or both, and causes operation of switch OD. Switch OD engages contacts OD8 so that a circuit is completed by way of contact DH for such floor below, brush BDB and contacts GO6 to cause operation of switch

XBHS and thus effect the answering of the down landing call for such floor below by the bottom compartment. If the highest call is a bottom compartment car call, it is answered by the bottom compartment, causing a high call reversal stop to be made. Should a down landing call be in registration for the same floor, it also is answered by the bottom compartment. Here again the engagement of contacts OD8 as a result of the operation of switch UFR completes a circuit from the DH contact for such floor by way of brush BDB and contacts GO6, 10 causing operation of switch XBHS to effect the answering of the down landing call. Also, when the highest calls are a bottom compartment car call and a down landing call for the floor next above, these calls are answered by the bottom and top compartments respectively with 15 a single stop, as above set forth.

As is customary in high call reversal operation, response to a down call on an up trip can not be made if there are calls above as the down call is not the highest call and switch HUD is maintained operated. Also a high call reversal stop can not be made when an up landing call is also in registration for the floor of highest call. This is because the circuit for the coil of switch HUD is maintained when an up landing call is answered. This is the case regardless of whether the circuits are arranged for the top compartment or the bottom compartment to pick up the up landing calls on the up trip. Assume that an up fourth floor landing call and a down fourth floor landing call are registered, with no calls for floors above. Switch HUD is maintained operated by the up fourth floor call so long as this call is registered, maintaining a feed to junction JU4 in the URSC circuit. Upon the picking up of the up fourth floor call, switch XTHS or XBHS is operated, depending upon whether the top or the bottom compartment picks up the call. This causes operation of switch ST which in turn causes release of switch GO. Switch GO engages contacts GO2' to maintain switch HUD operated after the cancellation of the up fourth floor call. This causes the car to remain set for upward travel. This enables the entering passenger to be carried to a floor above upon entering and registering a car call for such floor. Contacts ADV8' maintain the circuit for the coil of switch HUD until switch HHC closes during this operation, thus insuring that the top compartment will leave the fourth floor in the up direction.

Also a high call reversal operation is not had where an up landing call is in registration for a floor next below the one for which a down landing call or top compartment car call is registered. Assume that an up fourth floor landing call and a down fifth floor landing call are registered, with no calls for floors above. Again, upon the picking up of the fourth floor call, switch XTHS or XBHS is operated, depending upon whether the top or bottom compartment picks up the call. This causes release of switch GO which maintains switch HUD operated after the cancellation of the up fourth floor call, causing the car to remain set for upward travel. Thus in case the bottom compartment picks up the up fourth floor call, the down fifth floor call is not answered at the same time. In case the top compartment picks up the up fourth floor call, the down fifth floor call is not answered upon restarting the car unless the entering passenger registers a top compartment fifth floor car call and there is not an up fifth floor call, or call for a floor above. Thus a high call reversal stop is not made under conditions where an up landing call is registered for either or both floors at which the compartments are brought to a stop.

The system may also be arranged so that if a compartment is sufficiently loaded automatically to bypass landing calls which it would otherwise pick up, the other compartment picks up such calls. By closing knife switch K52, the top compartment is caused to pick up up land-

ing calls on up trips, under conditions where the bottom compartment is sufficiently loaded for automatic load bypass. Similarly, by closing knife switch K55, the bottom compartment is caused to pick up down landing calls on down trips under conditions where the top compartment is sufficiently loaded for automatic load bypass.

Assume first that knife switch K52 is closed, that knife switch K51 is open, that the car is set for upward travel, that the bottom compartment has sufficient load to cause operation of switch BLS, and that an up landing call is in registration, say for the fourth floor. Under such conditions, upon the engagement of brush of TUB with contact UH4, a circuit is completed by way of contacts OU10, ADV9 and BLS5 and switch K52 for the coil of switch XTHS. This switch operates as above described to cause the top compartment to be brought to a stop at the fourth floor. If switch BLS is not operated, contacts BLS5 are separated so that the bottom compartment is brought to a stop at the fourth floor. If switch K51 is also closed and there is present none of the conditions previously discussed for causing the bottom compartment to pick up the call, the top compartment picks up the call by way of contacts ACS2 as previously described. Assume that one or more of such conditions is present as say an up landing call is in registration for the fifth floor. Whereas, upon the engagement of brush TUB with contact WH4, contacts ACS2 are separated, contacts BLS5 are engaged so that the top compartment picks up the fourth floor call. When the car is set for downward travel, with switch K56 open, the top compartment picks up the down calls as previously described and, in case of a stop under conditions where there is a down call for a floor next below, the bottom compartment, when switch BLS is operated, does not respond to such floor below call because contacts BLS6 are separated.

Assume now that knife switch K55 is closed, that knife switch K56 is open, that the car is set for downward travel, that the top compartment has sufficient load to cause operation of switch TLS, and that a down landing call is in registration, say for the fourth floor. Under such conditions, upon the engagement of brush BDB with contact DH4, a circuit is completed by way of contacts OD8, ADV10 and TLS7 and switch K55 for the coil of switch XBHS. This switch operates as above described to cause the bottom compartment to be brought to a stop at the fourth floor. If switch TLS is not operated, contacts TLS7 are separated so that the top compartment is brought to a stop at the fourth floor. If switch K56 is also closed and there is present none of the conditions previously discussed for causing the bottom compartment to pick up the call, the bottom compartment picks up the call by way of contacts AC3 as previously described. Assume one or more of such conditions is present as say a down landing call is in registration for the third floor. Whereas upon the engagement of brush BDB with contact DH4 contacts ACS3 are separated, contacts TLS7 are engaged so that the bottom compartment picks up the call. When the car is set for upward travel, with switch K51 open, the bottom compartment picks up the up calls as previously described and, in case of a stop under conditions where there is an up call for a floor next above, the top compartment, when switch TLS is operated, does not respond to such floor above call because contacts TLS7 are separated.

The system may also be arranged so that, similar to the operation where one of the compartments is automatically load bypassing calls, if a compartment is removed from service, the other compartment picks up the landing calls. This has been explained for operation under night service conditions. The top compartment is removed from service under daytime operation by moving knife switch K33 to its lower position and closing

switch K34, causing operation of switch TCO. The bottom compartment is removed from service under daytime operation by moving knife switch K33 to its upper position and closing switch K32, causing operation of switch BCO.

So far there have been operations described whereby, under certain conditions, the top compartment picks up the up landing calls on the upward trip and the bottom compartment picks up the down landing calls on the downward trip. The system may be arranged so that the top compartment always picks up the up landing calls on the upward trip, and/or the bottom compartment always picks up the down landing calls on the downward trip, provided in each case the call is registered before the call pickup brush for that compartment engages the corresponding stationary contact. This is effected in case of the up landing calls by closing knife switch K53 and in case of the down landing calls, by closing knife switch K54.

Assume first that switch K53 is closed and again, for example, that an up landing call is in registration for the fourth floor. Upon the engagement of brush TUB with contact UH4 with the car set for upward travel, a circuit is completed by way of contacts OU10 and ADV9 and switch K53 for the coil of switch XTHS. Switch XTHS operates as above described to cause the car to be slowed down and brought to a stop with the top compartment at the fourth floor. Had the call been registered after brush TUB in its upward movement disengaged contact UH4, the top compartment does not pick up this call. However, upon the engagement of brush BUB with contact UH4, the call is picked up by way of contacts OU12 and ADV12 to cause the operation of switch XBHS. This brings the car to a stop with the bottom compartment at the fourth floor as previously described. Should an up call at the fifth floor be registered under the last assumed conditions before brush TUB engages contact UH5, the engagement of this brush and contact along with the engagement of brush BUB with contact UH4 causes the car to be slowed down and brought to a stop with the top compartment at the fifth floor and the bottom compartment at the fourth floor. The up hall lanterns for both floors are lighted incident to the picking up of the calls and the doors for both compartments are opened as the stop is made.

Assume that switch K54 is closed, that the car is set for downward travel and that a down landing call is in registration, say again for the fourth floor. Upon the engagement of brush BDB with stationary contact DH4, a circuit is completed by way of contacts OD8 and ADV10, and knife switch K54 for the coil of switch XBHS. This switch operates as previously described to cause the car to be brought to a stop with the bottom compartment at the fourth floor. Had the down fourth floor call been registered after brush BDB in its downward movement disengaged contact DH4, upon engagement of brush TDB with contact DH4 a circuit is completed by way of contacts OD6 and ADV11 for the coil of switch XTHS, causing the car to be brought to a stop with the top compartment at the fourth floor. Had, under the last assumption, a down third floor landing call been registered before the engagement of brush BDB with contact DH3, upon the engagement of this brush with this contact and the engagement of brush TDB with contact DH4, the car is caused to be slowed down and brought to a stop with the top compartment at the fourth floor and the bottom compartment at the third floor. The down hall lanterns at the fourth and third floors are lighted incident to the picking up of these calls and the doors for both compartments are opened as the car is brought to a stop.

The system may be arranged so that, instead of the call pickup operations previously described, one compartment always answers landing calls for even numbered floors

and the other compartment landing calls for odd numbered floors. This is effected by closing (in Figure 3) knife switches K30 and K31 and also say knife switches K53 and K54. The closing of switches K30 and K31

5 causes operation of alternate floor switch ALT which acts to separate contacts ALT1 and ALT2. The separation of contacts ALT1 disconnects from the + supply line selector contacts HZC for even numbered floors. Similarly the separation of contacts ALT2 disconnected from the + supply line selector contacts CZC for even numbered floors. In the operations previously described, due to the elongated brushes UHZB, DHZB, UCZB, DCZB, HZB and CZB, switches HAZ, CAZ, HZ and CZ were operated and thus contacts HAZ1, CAZ1, HZ2, HZ3, 15 CZ2 and CZ3 were engaged when the advance brushes and the call pickup brushes engaged live contacts in the call pickup circuits. However, with contacts ALT1 and ALT2 separated, contacts HZC and CZC for even numbered floors are not alive so that switches HAZ, CAZ, 20 HZ and CZ are not operated upon the engagement for each direction of car travel of their respective brushes with even numbered floor contacts. For a building with an odd number of floors, the stationary contacts for the next to the top floor as well as those for the top floor 25 would be connected directly to the + line. In the circuit illustrated this would mean that contacts HZC6 and CZC6 would be connected directly to line +. However, to illustrate subjecting contacts for more than one floor above the lobbies to switch ALT, contacts HZC6 and CZC6 are shown subject to contacts ALT1 and ALT2.

Assume that the car is set for upward travel and that an up landing call is again registered for the fourth floor. The alternate floor stop operation is controlled through the operation of switches HZ and CZ. Upon the engagement of brush HZB with contact HZC3, a circuit is completed for the coil of switch HZ which operates to engage contacts HZ2 so that upon the engagement of brush TUB with contact UH4, a circuit is completed for the coil of switch XTHS, causing the car to be slowed down and

40 brought to a stop with the top compartment at the fourth floor. Had the up fourth floor call been registered too late to be picked up by the top compartment, but before the engagement of brush BUB with contact UH4, the engagement of brush HZB with contact HZC4 does not

45 complete a circuit for the coil of switch HZ so that contacts HZ3 are separated. Thus the bottom compartment does not pick up the up fourth floor call. Had an up third floor call been registered instead of an up fourth floor call, upon the engagement of brush TUB with contact UH3, a circuit is not completed for the coil of switch XTHS as the engagement of brush HZB with contact HZC2 does not cause operation of switch HZ to engage contacts HZ2. Thus the top compartment does not pick up the up third floor call. However, the engagement of

50 brush HZB with contact HZC3 does cause operation of switch HZ so that the engagement of brush BUB with contact UH3 completes a circuit through contact HZ3 for the coil of switch XBHS, causing the car to be slowed down and brought to a stop with the bottom compartment 55 at the third floor.

60 It is believed that it will be seen from the above that during up car travel the top compartment picks up the up landing calls for even numbered floors and the bottom compartment picks up the up landing calls for odd numbered floors.

65 It is believed that it will also be seen that during down car travel the top compartment picks up the down landing calls for even numbered floors and the bottom compartment picks up the down landing calls for odd numbered floors. Briefly, this is effected by 70 causing operation of switch HZ by the engagement of brush HZB with contacts HZC for only odd numbered floors, thereby enabling brush BDB upon its engagement with live contacts DH for odd numbered floors to complete a circuit for the coil of switch XBHS and brush TDB upon its engagement with live contacts DH for even

numbered floors to complete a circuit for the coil of switch XTHS. Switch CZ is operated by the engagement of brush CZB with contacts for only odd numbered floors to cause for each direction of car travel the top compartment to respond to its car calls for even numbered floors and the bottom compartment to respond to its car calls for odd numbered floors.

Contacts CZ1, HZ1 and HUD4 act to maintain the coil of switch HUD energized and thus prevent high call reversal unless brush HZB or CZB is in engagement with a live stationary contact. Thus, for example, if the highest landing call is picked up by another car before brush HZB engages a stationary contact say contacts HZC4 subject to contacts ALT1, switch HZ not being operated when brush HZB engages contact HZC4, does not separate contacts HZ1. Thus switch HZ is maintained operated, preventing the stopping of the car with the bottom compartment at the fourth floor and the reversal of the direction of travel. Under such conditions, the bottom compartment would have to go to the fifth floor, one which it is scheduled to serve, before the reversal can be effected.

If it be desired to have each compartment stop in response to its car calls for all landings at the same time that in response to landing calls the top compartment stops only at even numbered floors and the bottom compartment stops only at odd numbered floors, this may be effected by closing knife switch K59 so that switch CZ is operated for each floor. By opening switch K31, the above described operation is had only under up peak traffic conditions at which time contacts VUP1 are in engagement.

The system may be arranged so that, when it is providing alternate floor stops as a result of the separation of contacts ALT1 and ALT2, if either compartment is sufficiently loaded automatically to bypass landing calls, the other compartment is caused to stop in response to landing calls at all floors. This is effected by closing knife switch K61. Thus if the top compartment, for example, has taken on a bypassing load, contacts TLS8 engage to complete a circuit for the coil of switch HZ to maintain the switch operated so long as the condition exists. Thus contacts HZ3 are maintained engaged to cause the bottom compartment to stop in response to all landing calls until room is again provided in the top compartment due to discharge of passengers. If the bottom compartment is loaded instead of the top compartment, contacts BLS7 are engaged causing the operation of switch HZ to engage contacts HZ2 and thus the top compartment to respond to all landing calls. The closing of knife switch K62 serves a similar purpose when either compartment is removed from service. The removal from service of the top compartment causes engagement of contacts TCO6 and of the bottom compartment causes engagement of contacts BCO5. The engagement of either of these contacts completes a circuit through switch K62 for the coil of switch HZ.

The system may be arranged so that a certain car serves only a certain group of floors with the floors not served by that car served by one or more other cars. This may be effected by means of the control of switches HZ and CZ, say subject to switch ALT. Assume, for example, that it is desired to prevent stopping of the car at the third, fourth and fifth floors as representative of an express zone. Contacts HZC2, HZC3, HZC4 and HZC5 would be rendered subject to contacts ALT1, contacts CZC2, CZC3, CZC4 and CZC5 would be rendered subject to contacts ALT2, and contacts HZC6, HZC7, CZC6 and CZC7 would be connected directly to the + line. Contacts CZ1, HZ1 and HUD4 maintain the coil of switch HUD energized and thus prevents high call reversal under such conditions at least until brushes HZB and CZB engage contacts HZC6 and CZC6 on the upward trip, thus preventing high call reversal in the express zone.

The system may also be arranged so that the bottom compartment does not stop at the upper of the two lobbies under certain conditions. This is effected in the case of landing calls by causing operation of switch HNLS, which separates contacts HNLS1 to prevent the operation of switch HZ upon the engagement of brush HZB with contact HZC2. Thus, because contacts HZ3 are separated, no circuit can be completed for the coil of switch XBHS to cause a stop of the bottom compartment at the second floor. In the case of car calls, this is effected by causing operation of switch CNLS which separates contacts CNLS1 to prevent the operation of switch CZ upon the engagement of brush CZB with contact CZC2. Thus because contacts CZ3 are separated no circuit can be completed for the coil of switch BCS to cause a stop of the bottom compartment at the second floor. Also contacts CNLS2 may be connected in circuit with tube BC2 and rendered effective by opening knife switch K60 to prevent the registration of the bottom compartment second floor car call and thus the lighting of the tube to indicate that such a call has been registered. It will be assumed that switch K60 is closed.

The operation of switches HNLS and CNLS may be effected under a variety of conditions. By closing knife switch K1, a circuit for the coil of switch HNLS is completed by contacts OD1 during downward travel. Thus the bottom compartment is unable to stop on its downward trip at the second floor in response to a down landing call for that floor. The closing of knife switch K6 causes a similar operation, completing a circuit through contacts OD2 for the coil of switch CNLS which acts to prevent stopping of the bottom compartment on its downward trip in response to its second floor car call. By closing knife switch K2, the circuit for the coil of switch HNLS is completed when the system is operating under down peak traffic conditions, at which time contacts VDP1 are engaged. Thus the bottom compartment can stop at the second floor in response to a second floor landing call except under down peak traffic conditions. Knife switch K7 and contacts VDP2 serve the same purpose in controlling the coil of switch CNLS. By closing knife switches K4 and K3, a circuit for the coil of switch HNLS is completed by contacts OU4 during upward car travel. Thus the bottom compartment during its upward travel cannot stop at the second floor in response to an up landing call for the second floor. Knife switches K8 and K10 and contacts OU5 serve a similar purpose for the bottom compartment second floor car call. By closing knife switch K4 while leaving knife switch K3 open, switch HNLS is operated to prevent response of the bottom compartment to an up landing call for the second floor during up car travel, unless the top compartment is sufficiently loaded to cause the separation of contacts TLS3. The same is true as regards a second floor car call for the bottom compartment when switch K8 is closed and switch 10 is open, unless contacts TLS4 are separated as a result of load in the top compartment. By closing switch K4 while leaving switch K3 open and moving switch K5 to its upper position, switch HNLS is operated to prevent response of the bottom compartment to an up landing call for the second floor during up car travel, unless the top compartment has a bypassing load separating contacts TLS3 and there is no car available for selection for up dispatching so that contacts NAC1 are separated. The coil of switch NAC is subject to contacts VB1 of the availability relay of each of the cars (a, b, c, d) so that if no car is available for selection, all of these contacts are closed and switch NAC is operated, separating contacts NAC1. With switch K5 in its lower position instead, such stopping is prevented unless the top compartment has a bypassing load indicated by the separation of contacts TLS3 and there is another car on its up trip with a bypassing load in its top compartment acquired at the upper lobby, indicated by the separation of contacts UTLC1 for such

other car. Switch UTLC for a car is operated when the top compartment of that car has a bypassing load, represented by the engagement of contacts TLS6 for that car, is at the upper lobby, represented by the engagement of contacts ML3 for that car, is set for up, represented by the engagement of contacts UD8 for that car and has its starting operation initiated, represented by the engagement of contacts SB5 for that car. Once operated, it becomes self held by contacts UTLC3 until the load is sufficiently reduced to effect the separation of contacts TLS6 or until the car becomes set for downward travel, resulting in the separation of contacts UD8. Switch K11 corresponds with switch K5, contacts NAC2 with contacts NAC1 and contacts UTLC2 with contacts UTLC1 and act to prevent the response of the bottom compartment to its second floor car call during up car travel unless the top compartment is loaded and, with switch K11 in its upper position, there is no car available for selection for up dispatching, represented by the separation of contacts NAC2, or with switch K11 in its lower position, there is another car leaving the lobbies with a bypassing load in its top compartment, indicated by the separation of contacts UTLC2 for such other car.

The above described arrangements in which the top compartment operates to and from the upper lobby and the bottom compartment to and from the lower lobby, with or without the various modified operations controlled by knife switches K1 to K11 inclusive, is especially suitable for installations wherein the lobbies are different levels of the main floor of the building, with appropriate steps or ramps, or for installations where moving stairways connect the lobbies. This may not be considered satisfactory for certain types of buildings in which it may be preferred to provide service whereby passengers entering either compartment on the down trip may be carried to another lobby. This involves providing the top compartment with a first floor car button and providing room below the first floor for the bottom compartment when the top compartment goes to the lower lobby.

A top compartment first floor car call registering tube TC1 is illustrated and is rendered effective by closing knife switch K58. When a call is registered on this tube with the car set for downward travel, a circuit is completed through contacts OD5 and WB4 for the coil of car call below switch CCB. This switch operates to separate contacts CCB1, preventing the energization of the coil of switch OU and thus the setting of the car for upward travel until a stop is made by the top compartment at the lower lobby. Assume first that with the car set for down a car call is registered in the top compartment for the lower lobby at a time when no call is in registration to cause the car to stop with the top compartment at the upper lobby. Under such conditions, the top compartment runs past the upper lobby direct to the lower lobby where it is brought to a stop as a result of the engagement of brush TCB with contact TCP1. A circuit cannot be completed for the coil of switch OU to set the car for upward travel until the car is brought to a stop with the top compartment at the lower lobby and contacts CCB1 are reengaged as a result of the pulsing out of the first floor call as the car comes to a stop. When this takes place, the circuit for the coil of switch OU is completed by way of brush RB, contact MLC0 and contacts H1 and CCB1. Should the car first come to a stop with the top compartment at the upper lobby under conditions where a top compartment lower lobby car call is in registration, a circuit is not completed for the coil of switch OU through brush RB, contact MLC1, and contacts H3 as contacts CCB1 remain separated. Thus upon expiration of the passenger transfer time, switch SB is again operated, starting the car in the down direction to answer the top compartment first floor car call. In this case, the cir-

cuit for the coil of switch SB is by way of contacts CCB2.

Assume now that the car is stopped with the top compartment at the upper lobby with no first floor car call registered for the top compartment. Under such conditions a circuit is completed for the coil of switch OU, causing the car to be set for travel in the up direction. Assume further that no car call is in registration for a floor above the lobbies so that switch HCC is not operated and that the car is not selected for up dispatching so that switches WB and WBX are not operated. Should the top compartment first floor car call be registered under such conditions, a circuit is completed through contacts HCC4, ML5 engaged with the car at the lobbies, WBX2 and WB4 for the coil of switch CCB. Switch CCB operates to separate contacts CCB1, causing the release of switch OU and operation of switch OD to set the car for downward travel. Switch OD also engages contacts OD5 to establish a holding circuit for the coil of switch CCB. Thus, subject to the expiration 20 of the passenger transfer time interval and closing of the doors, the car is started in the down direction to answer the first floor car call.

The hall lanterns at the upper lobby are controlled under the above assumed conditions properly to indicate 25 the direction in which the top compartment will leave the floor. Just before the engagement of brush TCB with contact TCP2 for picking up an upper lobby car call for the top compartment on its downward trip, brush LCB engages contact LC1 to complete a circuit for the coil of advance lobby switch ALR. This switch operates to separate contacts ALR1 to prevent the lighting of the down hall lantern DHL2 for the upper lobby unless a top compartment lower lobby car call is registered. With such lower lobby car call registered, contacts CCB3 are engaged so that upon the engagement of brush TDLB with contact DLC2 under conditions where the top compartment makes an intervening stop at the upper lobby, a circuit is completed to cause the lighting of the down hall lantern DHL2 at the upper lobby.

Under conditions where the top compartment goes to the lower lobby, an advance hall lantern operation is provided. This is effected by the operation of below the lobby switch BTL. The circuit for the coil of this 45 switch is completed by the engagement of brush LCB with contact LCO, slightly in advance of the engagement of brush TULB with contact ULC1. Thus a circuit for the up hall lantern UHL1 is completed through contacts MG5, TLS5, TDTS3 and BTL1, brush TULB, contact ULC1, and contacts BTL2 for the up hall lantern UHL1 for the lower lobby.

To enable the bottom compartment also to serve the upper lobby under conditions where the top compartment 55 also serves the lower lobby, at least switches K1 and K6 should be open. Operation under such conditions has already been described.

In the above described operation where a passenger entered the top compartment at the upper lobby and registered a car call for the lower lobby, it was assumed that the top compartment doors were open. This would be the case when there is to be a passenger transfer when the stop is made, as for example, where a top compartment upper lobby car call is registered, or when the doors are always opened when a stop is made by the top compartment at the upper lobby which can be the case when switch K36 is closed as will be explained later. Where the doors are not open unless a call has been responded to, it would be desirable, when an intending passenger at the upper lobby wished to be carried to the lower lobby under conditions where the top compartment is standing unselected at the upper lobby set for up with no car calls for floors above, to effect the opening of the doors in response to the intending 65 passenger registering a down landing call for the upper

lobby to enable him to enter the top compartment and register the lower lobby car call. This may be effected by closing knife switch K49, rendering the preparatory call below circuit effective. Should the down upper lobby call be registered under such conditions, switch ULD having its coil connected across load resistor RLD2 is operated to engage contacts ULD1 which under the assumed conditions completes a circuit for the coil of switch PCB by way of switch K49, contacts ML7, WD5, WBX3 and HCC5, and also through contacts CCB4 for each of the other cars of the system, it being further assumed that no switch CCB for any other car is operated. Switch PCB operates to engage contacts PCB3 to connect capacitor C16 across its coil and also separates contact PCB1 to prevent operation of switch SE. It also engages contacts PCB2 to complete a circuit for the coil of switch CCB. Switch CCB operates to release switch OU and thus cause operation of switch OD to set the car for downward travel. Switch OD engages contacts OD6, completing a circuit for the coil of switch XTHS, which switch operates as previously described to cause through operation of switch TDTS the opening of the doors for the top compartment. Also, it causes automatic cancellation of the down upper lobby call, with the result that switch ULD releases. Switch PCB does not release immediately when disconnected from the supply lines by the separation of contacts ULD1, being delayed by the discharge of capacitor C16 for a time sufficient to enable the passenger to enter the top compartment and register his car call and thus maintain switch CCB operated and the car set for down. This arrangement is also of advantage for night service operation with both compartments and also for single compartment operation where the top compartment is providing the service.

It also may be considered desirable for certain installations to provide service whereby passengers in the bottom compartment may be carried to the top floor. This may be effected by closing knife switch K57, rendering tube BC7 effective for registering calls. When such call is registered, it maintains switch HCC operated until that call is answered by bringing the bottom compartment to a stop at the top floors. Thus a reversal operation is prevented when a stop is first made with the bottom compartment at the sixth floor. When hook switch HC7 is opened to break the circuit for the coil of switch HCC, the engagement of contact HCC1 completes a circuit for the coil of switch UFR, provided the car is not subject to down timed dispatching so that contacts VD1 are separated. Also, upon the engagement of brush BCB with contact BCP7, switch BCS is operated. Switch UFR operates to engage contacts UFR3 and switch BCS operates to engage contacts BCS2, thereby causing operation of switch ST and thus the stopping of the car with the bottom compartment at the top floor. Also operation of switch ST is assured under the assumed conditions by the engagement of brush TSB with contact TC7. When a bottom compartment car call exists for the top floor, the engagement of brush BCUAB with contacts BCP7 completes a circuit for the car call controlled coil of switch ACS. The resultant separation of contacts ACS1 prevents the completion of a circuit for the coil of switch ST through brush TSB, thereby preventing stopping of the car with the bottom compartment at the sixth floor and the top compartment at the seventh floor unless a call is being answered by a compartment for one of these floors. When contacts VD1 are separated, a circuit is completed for the coil of switch UFR through brush UTRB and contacts UTRC7 when the bottom compartment comes to a stop at the seventh floor, thereby causing operation of switch UFR to separate contacts UFR1 and thus causing the setting of the car for downward travel as the stop is made. It is to be understood that, under

such conditions, room is provided in the hoistway overhead to accommodate the top compartment.

It is preferred under conditions where the bottom compartment serves the top floor to enable the car to be selected for down dispatching with the bottom compartment at the next to the top floor or at the top floor. This may be effected by elongating contact SDT of Figure 5 of the aforesaid Glaser and Hornung Patent No. 2,589,242 so as to extend the distance of the two floors. Thus the car is available for selection at either floor. When the car is selected, switch WT is maintained operated and the selection of another car is prevented, until the bottom compartment leaves the next to the top floor on its downward trip. Thus, for example, should the bottom compartment, after being dispatched from the top floor on its downward trip, make a stop at the next to the top floor or should the top compartment make a stop at the top floor, the hall lanterns for that car at such floors are lighted to the exclusion of those for another car available for down selection. Incident to such operation, when switch DDS is operated in response to the engagement of contacts WTX1, it establishes a self holding circuit through contacts DDS2 and VT3 until the bottom compartment leaves the next to the top floor on its downward trip. Thus contacts DDS3 are engaged to maintain switch DIS operated and thus enable the car to be started down after a stop of the bottom compartment at the next to the top floor after its return thereto from the top floor.

In the examples of operation so far given, the doors for a compartment open automatically when a stop is made by that compartment at a floor for which a landing call for the direction of car travel or a car call for that compartment is registered. Also, the doors for the compartments are opened at the top floors and lobbies only in the event that in each case the compartment is responding to a call. This operation may be varied. Assume first that knife switch K36 is closed. This causes operation of switch TDO to open the door for top compartment passenger transfer every time the top compartment stops at a given floor. The circuit for the coil of the top compartment door open switch TDO under such conditions is through contacts TOT3, selector contact DOC3 for such given floor, brush DOBT, switch K36, contacts 1SP5 and switch DZ2. Contact DOC3 may be for any selected floor, say the top floor or the upper lobby. Like contacts for several floors may be provided when such operation is considered desirable for such floors. A similar operation is provided for the bottom compartment by closing knife switch K42 in which case the circuit for the coil of the bottom compartment door open switch BDO is through contacts BOT1, selector contact DOC1, brush DOBB1, switch K42, contacts 1SP1 and switch DZ1. Here again contact DOC1 may be for any selected floor and like contacts may be provided for several floors. In each case the compartment doors continue to be opened when the compartment is answering a call when the stop is made.

Assume now that knife switches K37, K38 and K39 are closed. Under such conditions, a circuit is completed for the coil of switch TDO to effect a door opening operation for the top compartment every time a stop is made. With switches K37 and K38 closed and switch K39 open, a door opening operation for the top compartment is effected every time a stop is made, except on a high call reversal stop with no call to be responded to by the top compartment. The prevention of such door opening operation is effected by contacts UFR4 which separate to prevent the completion by way of switches K37 and K38 of the circuit for the coil of switch TDO when such high call reversal stop is made. Contacts H14 maintain this circuit open after the stop is made. With switches K37 and K39 closed and switch K38 open, a door opening operation for the top compartment is made at every floor at which a stop is made,

unless the top compartment is load bypassing in which case contacts TLS10 are separated. With switch K37 closed and switches K38 and K39 open, a combination of the last two described operations is obtained. The same operation is provided for the bottom compartment by knife switches K43, K44 and K45, these switches corresponding to switches K37, K38 and K39 respectively. Also contacts BLS1, H4 and UFR2 correspond to contacts TLS10, H14 and UFR4 respectively. By closing knife switch K46, the doors for the bottom compartment are opened each time the bottom compartment on an upward trip stops at the upper lobby under conditions where the top compartment has a bypassing load. The circuit for the coil of switch BDO under such conditions is through contacts BOT1, selector contact DOC2, brush DOBB2, contacts OU3, TLS1 and BLS2, and switch K46.

By closing knife switch K40, the doors for the top compartment, if opened when a stop is made, are prevented from closing, under conditions where the doors for the bottom compartment are being held open say as a result of a person maintaining the touch on the landing button for the direction of travel of the car for the floor at which the bottom compartment is stopped. This is effected by contacts BDTS8 which remain engaged to maintain the circuit through contacts TDO9 and switch K40 for the coil of switch TDO so long as contacts BDTS1 maintain the circuit for the coil of switch BDO. The coil of switch BDTS is maintained connected to the supply lines until the finger is removed or switch TOT or BOT times out to cause operation of switch SB. A corresponding operation to maintain the doors for the bottom compartment open is provided by closing knife switch K47, contacts TDTS1 and BDO4 corresponding in this circuit with contacts BDTS8 and TDO9.

Further variations in the control of the operation of the doors are provided by the closing of knife switches K12 to K17. Assume first that switches K13 and K14 are closed. Under such assumption, when the car is stopped under conditions where the doors for the top compartment are opened and a person desires to delay the closing of these doors, he may do so by touching and maintaining touched the landing button for the direction of car travel at the floor at which the top compartment is stopped, provided the time intervals of switches TDTS and TOT have not expired. The touching of the landing button under such conditions causes operation of switch XTHS which in turn causes operation of switch THS as previously described. Switch THS engages contacts THS1 to reconnect through contacts SB1 and TDO1 the coil of switch TDTS to the supply lines, thereby maintaining contacts TDTS5 engaged to maintain a circuit completed through contacts TOT2 for the other coil of switch TOT. Thus, so long as the touch is continued, contacts TOT1 are separated, preventing the operation of switch SB. As a result contacts SB1 remain engaged, so that the coil of switch TDTS remains connected to the supply lines. This maintains contacts TDTS4 engaged which in turn maintains switch TDO operated and thus the doors in open condition. With switches K13 and K14 open, switch SB would be operated upon the release of switch TOT after expiration of its time interval, even though touch of the landing button is maintained. A similar operation is provided for the bottom compartment by closing knife switches H16 and K17, contacts BDTS6 and BOT3 in the circuit for the other coil of switch BOT corresponding to contacts TDTS5 and TOT2.

In the previous example with switches K13 and K14 closed, it may be considered desirable not only to be able to hold open the doors by maintaining the touch of the landing button but to reopen the doors if the time interval provided by switch TDTS has expired. This may be effected by closing knife switch K21. Assume first that switches K13 and K14 are open and switch K21 is closed. When switch TDTS releases, it separates contacts TDTS4, 75

causing the release of switch TDO to effect the closing of the doors. If the landing button is touched before switch TOT releases at the end of the passenger transfer period to cause operation of switch SB, the engagement of contacts THS1 as a result of touching the button completes through contacts SB1 and switch K21 a circuit for the coil of switch TDTS to cause reoperation of the switch and thus the reopening of the doors. As soon as switch TOT times out to engage contacts TOT1, with the engagement of contacts BOT2 a circuit is completed for the coil of switch SB. Switch SB operates to separate contacts SB1, disconnecting the coil of switch TDTS from the supply lines. Thus when switch TDTS times out, the doors are reclosed. With switches K13 and K14 closed, the reoperation of switch TDTS causes engagement of contacts TDTS5 so that if the landing button is touched before switch TOT releases, the doors may not only be reopened but also may be retained in open position by maintaining the touch of the landing button as above explained. Switch K26 serves a similar purpose for the bottom compartment.

Assume now that it is desired to hold up the closing of the doors of the other compartment when a landing button is touched at a floor to hold up the closing of the doors for the compartment stopped at that floor. This is effected by closing switches K12, K13, K14, K15, K16 and K17 and also certain of the knife switches subject to contacts TOT2 and BOT2, say switches K37, K38, K39, K43, K44 and K45. Assume that under such conditions, the landing button is touched for the floor at which the bottom compartment is stopped. This causes operation of switches XBHS and BHS, as previously described. Switch BHS engages contacts BHS1 to reconnect through contacts SB4 and BDO3 the coil of switch BDTS to the supply lines. Switch BDTS maintains contacts BDTS4 and BDTS6 engaged and thus switches TOT and BOT operated so long as the finger is held on the button. Switch BOT acts as above described to prevent operation of switch SB so as to maintain the coil of switch BDTS connected to the supply lines, thus maintaining the bottom compartment doors open until the touch is discontinued. Switch TOT acts to maintain contacts TOT3 engaged which in turn maintains switch TDO operated and thus the doors for the top compartment open until the touch is discontinued.

Should the landing button touched be the one for the floor at which the top compartment is stopped, switches XTHS and THS are operated. Switch THS engages contacts THS1 to reconnect through contacts SB1 and TDO1 the coil of switch TDTS to the supply lines. Switch TDTS maintains contacts TDTS5 and TDTS7 engaged and thus switches TOT and BOT operated so long as the finger is held on the button. Switch TOT acts to prevent operation of switch SB, thus maintaining the coil of switch TDTS connected to the supply lines, and as a consequence the top compartment doors open until the touch is discontinued. Switch BOT acts to maintain contacts BOT2 engaged and thus the doors for the bottom compartment open until the touch is discontinued.

In the above example, with switches K21 and K26 closed, the doors can be reopened as well as held open, so long as the button is touched before switches TOT and BOT time out. Also, with knife switches K21 and K26 closed, when a stop is made under conditions where the doors for only one compartment are opened, touching the landing button for the direction of car travel at the floor at which the other compartment is stopped to effect the opening of the doors for such other compartment maintains the doors for such one compartment open, provided the button is touched before expiration of the time interval for the initial time switch OT for such one compartment. Assume for example that a stop is made under conditions where, due to the fact that a landing call is being responded to for the floor at which the top compartment is stopped, the doors open for the

top compartment but, due to no call being responded to for the floor below, the doors for the bottom compartment are not opened. Notwithstanding the fact that switch BOT times out ahead of switch TOT under such conditions, so long as the landing button at the floor at which is stopped the bottom compartment, is touched before switch TOT times out, the resultant engagement of contacts BDTS4 maintains switch TOT operated and thus prevents separation of contacts SB4 so that the engagement of contacts BHS1 causes operation of switch BDTS to effect the opening of the doors for the bottom compartment.

If switches K14 and K17 are closed and switches K12, K13, K15 and K16 are open, both landing buttons for the direction of car travel must be held touched in order to maintain the doors for both compartments open. Under such conditions, the touching of the buttons before switches TOT and BOT time out causes engagement of contacts THS1 and BHS1 to connect the coils of switches TDTS and BDTS respectively to the supply lines, thereby engaging contacts TDTS6 and BDTS5 to complete a circuit for the other coil of switch TOT and engaging contacts BDTS7 and TDTS8 to complete a circuit for the other coil of switch BOT. Thus the doors for both compartments are maintained open until the touch of one or both of the buttons is discontinued.

It may be considered desirable for certain installations to enable the doors of a compartment to be opened, reopened or maintained open after the operation of switch SB so long as the doors of the other compartment are not within a certain distance of closed position. This is particularly applicable to the condition where the doors for such other compartment are closing but have not reached fully closed position. This operation is obtained with switches K20 and K25 closed. In describing this operation it will be assumed that switches K21 and K26 also are closed. Switches BDCL1 and TDCL2 are open when the doors for the bottom compartment and the top compartment respectively are within such certain distance from closed position. Assume that, after the time intervals of switches TOT and BOT expire to cause operation of switch SB and thus the separation of contacts SB1, a person touches the landing button for the direction of travel of the car at the floor at which the top compartment is stopped. If this takes place while say the doors for the bottom compartment are closing but before they reach a position to cause opening of switch BDCL1, a circuit is completed by way of switches K20 and BDCL1, contacts THS1 and switch K21 for the coil of switch TDTS. Switch TDTS acts as previously described to open, reopen or hold open the doors for the top compartment, depending on their status at the time that the button is touched. If the doors for the bottom compartment are in position in which switch BDCL1 is open, the top compartment doors can still be reopened provided knife switch K22 is closed and the button is touched before the doors for the top compartment say in closing have not reached the point where switch TDCL1 is opened. If a person touches the landing button for the direction of car travel for the floor at which the bottom compartment is stopped while switch TDCL2 is closed, a circuit is completed by way of switches K25 and TDCL2, contacts BHS1 and switch K26 for the coil of switch BDTS. This switch acts to open, reopen or hold open the doors for the bottom compartment, depending on their status at this time. With switch K27 closed, the bottom compartment doors are reopened even if switch TDCL2 is open provided the doors for the bottom compartment are in position in which switch BDCL2 is closed.

For some installations it may be considered preferable to enable the doors of a compartment to be opened, reopened or maintained open after the operation of switch SB under conditions where the doors for the other compartment are opening but have not reached a point within a certain distance of fully open condition. This opera-

tion is had when switches K23 and K28 are closed. Switches BDOL2 and TDOL1 in these circuits are opened when the doors in opening reach such certain distance from fully open condition. Assume that a person touches the landing button for the direction of car travel at the floor at which the top compartment is stopped, under conditions where the doors for the bottom compartment are opening but have not reached a point to cause opening of switch BDOL2. This completes a circuit by way of switch K23, contacts BDO2, switch BDOL2, contacts THS1 and switch K21 for the coil of switch TDTS, causing the opening, reopening or holding open of the doors for the top compartment. Switch K28, contacts TDO2, switch TDOL1, contacts BHS1 and switch K26 serve the same purpose in the corresponding circuit for the coil of switch BDTS.

Contacts H2 and H6 act to prevent opening, reopening or holding open of the doors in response to the say inadvertent touching of the top compartment car button or bottom compartment car button respectively for the floor at which such button is stopped.

With knife switches K24 and K29 closed, a longer time interval is provided for switches TDTS and BDTS in case of a stop in response to a landing call for the floor at which is stopped the compartment for which the switch is provided. Whereas such an arrangement is provided for switches TOT and BOT, such arrangement does not delay the initiation of the door closing operations. With switch K24 closed, when a landing call is picked up by the top compartment, the resultant engagement of contacts THS1 causes charging of capacitor C12 so as to delay further the release of switch TDTS. Similarly, when the bottom compartment picks up a landing call, the resultant engagement of contacts BHS1 causes charging of capacitor C14 so as to delay further the release of switch BDTS. With knife switches K35 and K41 closed, the circuits are arranged so that, once a door opening operation is initiated, the doors continue to fully open condition before a door closing operation can take place. This is effected by door open limit switches TDOL2 and BDOL1 which, with switches K35 and K41 closed, enable holding circuits to be established through contacts TDO7 and BDO1 for the coils of switches TDO and BDO respectively, upon operation of these switches to open the doors controlled thereby, until the doors reach open condition.

As a modification of the load weighing circuits, these circuits may be arranged so that, instead of rendering bypassing by both compartments subject to each load switch (BLS, TLS) being operated, bypassing by both compartments is subject to the total load in the two compartments, regardless of the relative amounts of these loads. Such an arrangement is shown in Figure 9. In this arrangement, the coil of a total load switch SLS is subject to two load weighing resistors TRL and BRL, one for each compartment, connected in parallel. An increase in load in each compartment decreases the amount of the resistor for that compartment which is connected in circuit with the coil of switch SLS, thus increasing the current supplied to the coil. Where the total current fed from the two paths reaches a certain value, switch SLS operates, even though there is not enough load in one of the compartments to operate the load switch for that compartment. Switch SLS engages contacts SLS1 and SLS2 to cause operation of load switches BLS and TLS respectively.

By closing knife switch 63, the system can be arranged so that, when operating to provide alternate floor stops, with car buttons for both even and odd numbered floors in each compartment effective (switch K59 closed), where the bottom compartment stops at an even numbered floor in response to a car call for such floor or the top compartment stops at an odd numbered floor in response to a car call for such floor, the other compartment answers the landing call for the direction of travel for

the floor at which it is brought to a stop. This is effected by contacts GO8' which close when such stop is initiated, causing operation of switch HZ to engage contacts HZ2 and HZ3 and thus rendering the top compartment effective to answer a landing call at an odd numbered floor and the bottom compartment effective to answer a landing call for an even numbered floor respectively.

From the above it will be seen that there is provided a control system for a multicompartiment car in which a variety of different operations is provided. As applied to a double compartment car, according to one arrangement, during up trips the bottom compartment picks up the up landing calls to initiate stopping of the car and during down trips the top compartment picks up the down landing calls to initiate stopping of the car. Both compartments stop for their car calls during travel in each direction. The calls are picked up in the order of the floors for each direction of travel, regardless of the order in which the picked up calls are registered. If, when the bottom compartment answers an up landing call or car call on an up trip, there is also an up landing call registered for the next floor above, this call is responded to by the top compartment so that the up hall lanterns at both of such floors are lighted, both calls are automatically canceled and the doors for both compartments are opened as the stop is made. Similarly, if when the top compartment picks up a down landing call or car call on a down trip, there is also a down landing call registered for the next floor below, this call is responded to by the bottom compartment so that the down hall lanterns at both of such floors are lighted, both calls are automatically canceled and the doors for both compartments are opened as the stop is made.

According to another arrangement, during up trips the top compartment picks up each up landing call to initiate stopping of the car with the top compartment at the floor for which such call is registered, except that the bottom compartment answers the call under conditions where a bottom compartment car call is in registration for the same floor or an up landing call or top compartment car call is in registration for the floor next above. Also, during down trips, the bottom compartment picks up each down landing call to initiate stopping of the car with the bottom compartment at the floor for which such call is registered, except that the top compartment answers the call under conditions where a top compartment car call is in registration for the same floor or a down landing call or bottom compartment car call is in registration for the floor next below.

Instead of the arrangement in which for each direction of car travel the following compartment picks up the landing calls for that direction or the leading compartment picks up the landing calls for that direction, as above set forth, the system may be arranged so that for one direction of car travel the following compartment picks up the landing calls for that direction and for the other direction of car travel the leading compartment picks up the landing calls for that direction. With this arrangement one compartment bears the brunt of the service and the other compartment takes care of landing calls not handled by such one compartment, as for example where there are landing calls for the direction of car travel for adjacent landings.

High call reversal operation on an up trip is provided, as under night service or up peak conditions, or where the cars are subject to down timed dispatching and a car is late in arriving at the top floors. Under such operation, if the highest call is a down landing call or a top compartment car call, the call is answered by the top compartment and the car is set for downward travel at the floor at which the stop is made, regardless of whether the system is arranged for the bottom compartment or the top compartment to answer up landing calls on an up trip. When such a high call is picked up under conditions where a down landing call is also in regis-

tration for the floor next below, this call is answered by the bottom compartment. If the highest call is a bottom compartment car call, the call is answered by the bottom compartment and the car is set for down travel at the floor at which the stop is made, regardless of whether the system is arranged for the bottom compartment or top compartment to answer up landing calls on an up trip. When such a high call is picked up under conditions when there is a down landing call in registration for the same floor, the down landing call is also answered by the bottom compartment.

The manner in which the bottom compartment responds to calls at the upper of the two lobbies may vary, especially under conditions where the car is subject to dispatching from the lower lobbies. Such variations would depend upon the requirements of the particular installation. The system may be arranged so that on a downward trip the bottom compartment does not stop at the upper lobby in response to a down landing call and/or a car call, or arranged so that it does not do so under down peak conditions. Also it may be arranged so that on an upward trip the bottom compartment does not stop at the upper lobby in response to an up landing call and/or a car call, or arranged so that it does not do so unless the top compartment has a certain load, or arranged so that it does not do so unless the top compartment has a certain load and there is no car available for selection for up dispatching, or arranged so that it does not do so unless the top compartment has a certain load and there is another up travelling car, the top compartment of which has a certain load acquired at the upper lobby.

The system may be arranged so that both compartments serve both lobbies. In such case where the top compartment has a lower lobby car call, the top and bottom compartments will pass the upper and lower lobbies respectively on the downward trip if no call exists for effecting a stop thereby at such floors and the car can not be set for upward travel until the top compartment lower lobby car call is answered. This operation is obtained not only in response to a previously registered top compartment lower lobby car call, but when the top compartment is stopped at the upper lobby set for up but not selected for dispatching, with no call for a floor above the lobbies, the top compartment may be caused to travel to the lower lobby in response to such call. The hall lanterns at the lobbies are controlled under such conditions properly to indicate the conditions to intending passengers at these floors.

Also, the system may be arranged so that both compartments serve both top floors. Here again, when the bottom compartment has a top floor car call, the top and bottom compartments will pass the top and next to top floors respectively on their upward trip if no call exists for effecting a stop thereby at such floors and the car can not be set for down until the bottom compartment top floor car call is answered. The system may also be arranged so where both compartments serve both top floors, the car may be selected for down dispatching with the bottom compartment at either of these floors. The hall lanterns at the top floors are controlled under such conditions properly to indicate the conditions to intending passengers at these floors. When the car is dispatched down with the bottom compartment at the top floor, another car can not be selected until the bottom compartment leaves the next to the top floor on its downward trip. Thus the down hall lanterns for the dispatched car are lighted to the exclusion of those for another car when the car makes a stop on its downward trip with the top compartment at the top floor and the bottom compartment at the next to the top floor.

Also, the system may be arranged so that, if either compartment is cut out of service, the other compartment responds to all landing calls. This is especially suitable for night service. When the bottom compartment is cut

out of service, the top compartment may be caused to travel to the lower lobby in response to a top compartment lower lobby car call or an up lower lobby landing call. Also, when the top compartment is cut out of service, the bottom compartment may be caused to travel to the top floor in response to a bottom compartment car call or down landing call for the top floor.

The system may be arranged so that the up landing calls are always picked up by the top compartment on the upward trip and/or the down landing calls are always picked up by the bottom compartment on the downward trip, provided in each case the call is registered in time to be picked up. If not, the call is then picked up by the following compartment provided it is registered in time to be picked up by that compartment. Also, it may be arranged so that if a compartment is sufficiently loaded automatically to bypass landing calls which would otherwise pick up, the other compartment picks up such calls. Also, the system may be arranged so that one compartment answers landing calls for even numbered floors and the other compartment answers landing calls for odd numbered floors, with each compartment answering its car calls for the floors for which it responds to landing calls or its car calls for all floors. With the system operating to provide alternate floor stops by the compartments in response to landing calls, it may be further arranged so that if either compartment is sufficiently loaded automatically to bypass landing calls and/or is removed from service, the other compartment is caused to stop in response to all landing calls. Also, the system may be arranged so that the compartments do not stop at floors of a certain group, thereby providing an express zone.

The system may be arranged so that the doors for a compartment open when a stop is made, only in the event that the compartment is responding to a call. This may include stops at the lobbies and at the top floors. Also, under night service conditions, the doors for a compartment, if opened upon a lobby stop, may reclose to enable the compartment to park with the doors closed. Thus there will be occasions, under both double compartment operation and single compartment operation with the top compartment, where the top compartment will be stopped at the upper lobby with its doors closed. The system may be further arranged so that, with the system arranged so that the top compartment can serve the lower lobby either under single compartment or double compartment operation, the registering of a down upper lobby call, under conditions where the top compartment is stopped at the upper lobby floor with its doors closed and set for up, with no car call registered for either compartment for a floor above and, if under dispatching, with the car not selected, effects the opening of the doors to enable the intending passenger to enter the car and register a lower lobby car call.

Also, the system may be arranged always to open the doors of a compartment when a stop is made by that compartment at a certain floor or floors, which may be the lobbies or top floors. Also, the system may be arranged so that the doors of a compartment open every time a stop is made, or every time a stop is made except on a high call reversal stop, and/or every time a stop is made when the compartment is not automatically bypassing landing calls because of its load. Also, the doors of the bottom compartment may be opened each time that compartment on its upward trip makes a stop at the upper lobby under conditions where the top compartment has a bypassing load.

When a compartment is stopped at a floor with its doors closed, the doors may be opened by registering a landing call for the direction of car travel for the floor at which the compartment is stopped. Also the doors may be maintained open by maintaining registered the landing call, at least until the passenger transfer time interval expires.

Also, the system may be arranged so that compartment doors, if opened when a stop is made, and the other compartment doors are being maintained open by maintaining registration of a landing call, are prevented from closing until after the passenger transfer time interval has expired. Also, the system may be arranged so that the doors for a compartment may be delayed in closing by registering the landing call for the floor at which the compartment is stopped, provided it is registered before the passenger transfer interval has expired. Under such conditions, the doors may be delayed in closing so long as the call is maintained registered. Also, the system may be arranged so that the doors may be reopened after their closing has been initiated, provided the call is registered before the passenger transfer time has expired. In such case, the doors may thereafter be maintained open so long as the call is maintained registered. Also, the system may be arranged so that the holding up of the closing of the doors of one compartment, so long as the call for the floor at which the compartment is stopped and for the direction of car travel is registered, also holds up the closing of the doors for the other compartment so long as the call is maintained registered, provided the call is registered before the passenger transfer interval expires. Also, the system may be arranged so that the registration before the expiration of the passenger transfer time interval of a call for the direction of car travel and for a floor at which a compartment is stopped to open the doors for that compartment, maintains the doors for the other compartment open. Also, the system may be arranged so that landing calls for the direction of car travel for the floors at which both compartments are stopped must be registered before the passenger transfer time interval expires in order to maintain the doors for the compartments in open position.

Also, the system may be arranged so that the doors for one compartment may be opened, reopened or maintained open even after the passenger transfer time interval has expired, provided the call for the direction of car travel for the floor at which the compartment is stopped is registered before the doors for the other compartment in closing reach a point a certain distance from closed position and/or even if they have reached this point, the doors of the one compartment may be reopened provided they have not reached a point a certain distance from closed position by the time that the call is registered. Also, the system may be arranged so that the doors of a compartment may be opened, reopened or maintained open, provided the call for the direction of car travel for the floor at which the compartment is stopped is registered before the doors for the other compartment in opening reach such open condition.

Throughout the description, reference has been made to various knife switches by means of which the system may be arranged so that different operations are provided. It is to be understood that the inclusion of these knife switches in the drawings does not mean that they would be provided in an actual installation. They are included as a convenient way to illustrate arrangements which may be utilized in various installations and whether or not any of such switches would be included in actual installations would depend upon the requirements of such installations.

As changes can be made in the above described system and many apparently different embodiments of this invention can be made without departing from the scope thereof, it is intended that all matter contained in the above description or shown on the accompanying drawings be interpreted as illustrative only and not in a limiting sense.

What is claimed is:

1. In an elevator installation; a plurality of floors; an elevator car having a plurality of superimposed compartments adapted to serve said floors; car actuating and stopping mechanism; a plurality of landing call register-

ing means, one for each of said floors; means responsive with the car set for travel in a given direction to calls that are registered by said landing call registering means for causing operation of said mechanism to stop always the same one of said compartments at the floors for which such calls are registered in the order of such floors, whereby one stop for each call is made in answering such calls, provided that such calls are not for adjacent floors; and means operable under conditions where such calls are in registration for a pair of adjacent floors for modifying operation of said mechanism to cause it to stop said one compartment and an adjacent compartment at such adjacent floors, whereby but one stop for such calls for a pair of adjacent floors is made in answering such calls, regardless of the adjacent floors for which such calls exist.

2. In an elevator installation; a plurality of floors; an elevator car having a plurality of superimposed compartments adapted to serve said floors; car actuating and stopping mechanism; a plurality of landing call registering means, one for each of said floors; means responsive with the car set for travel in a given direction to calls that are registered by said call registering means for picking up such calls to cause operation of said mechanism to bring a given one of said compartments to a stop at the floors for which such calls are registered in the order of such floors, whereby all of such calls are answered by the same compartment, provided that at the time that each such call is to be picked up there is no call registered by said call registering means for a floor adjacent the one for which said to be picked up call is registered; and means operable under conditions where with the car set for travel in said given direction there are calls registered by said call registering means for adjacent floors for causing operation of said mechanism to bring said one compartment and a compartment adjacent thereto to a stop at such adjacent floors, whereby both of such calls are answered with the same stop.

3. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said call registering means for picking up such calls to cause operation of said mechanism to bring a given one of said compartments to a stop at the floors for which such calls are registered in the order of such floors, regardless of the floors for which such calls are registered, provided that at the time that each such call is to be picked up there is no call registered by said call registering means for a floor adjacent the one for which said to be picked up call is registered; and means operable under conditions where with the car set for travel in said given direction there are calls registered by said call registering means for a pair of adjacent floors for causing operation of said mechanism to bring the leading compartment to a stop at the farther of such adjacent floors and the following compartment to a stop at the nearer of such adjacent floors in response to such calls for such floors, regardless of the adjacent floors for which such calls exist.

4. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said landing call registering means for picking up such calls to cause operation of said mechanism to stop a given one of said compartments at the floors for which such calls are registered in the order of such floors; and means responsive with the car set for travel in said given direction to calls registered by said landing call registering means for a pair of adjacent floors for preventing operation of said mechanism to

stop said one compartment at both of such adjacent floors and to cause operation of said mechanism to stop the leading compartment at the farther of such adjacent floors and the following compartment at the nearer of such adjacent floors, regardless of the adjacent floors for which such calls exist.

5. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said landing call registering means, for causing operation of said mechanism to stop a given one of said compartments at the floors for which such calls are registered in the order of such floors, whereby one stop for each call is made in answering such calls, provided that such calls are not for adjacent floors; and means operable under conditions where with the car set for travel in said given direction calls are registered by said landing call registering means for a pair of adjacent floors for modifying operation of said mechanism to cause it to stop the leading compartment at the farther of such adjacent floors and the following compartment at the nearer of such adjacent floors in response to such calls for such floors, whereby but one stop for such calls for a pair of adjacent floors is made in answering such calls, regardless of the adjacent floors for which such calls exist.

30 6. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to calls that are registered by said landing call registering means for causing operation of said mechanism to stop in the order of floors a given one of said compartments at the floors for which such landing calls are registered; and means operable under conditions where with the car set for travel in said given direction there is a call registered by the leading compartment car call registering means for a floor next beyond one for which there is a landing call registered by said landing call registering means for modifying operation of said mechanism to cause it to stop the leading compartment at such floor beyond and the following compartment at the floor for which such landing call is registered, in response to such calls, regardless of which compartment is said given one.

7. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to calls that are registered by said landing call registering means for causing operation of said mechanism to stop in the order of floors a given one of said compartments at the floors for which such landing calls are registered; and means operable under conditions where with the car set for travel in said given direction there is a call registered by the following compartment car call registering means for a floor next preceding one for which there is a landing call registered by said landing call registering means for modifying operation of said mechanism to cause it to stop the following compartment at such preceding floor and the leading compartment at the floor for which such landing call is registered, in response to such calls, regardless of which compartment is said given one.

8. In an elevator installation; a plurality of floors; an elevator car having a pair of superimposed compartments adapted to serve said floors; car actuating and stopping

mechanism; a plurality of landing call registering means, one for each of said floors, means responsive with the car set for travel in a given direction to calls that are registered by said landing call registering means for picking up such calls to cause operation of said mechanism to stop in the order of floors the leading compartment at the floors for which such calls are registered; and means responsive with the car set for travel in said given direction to a call registered by said landing call registering means for a floor next beyond one for which a landing call is registered by said landing call registering means for preventing operation of said mechanism to stop said leading compartment at said one floor and to cause operation of said mechanism to stop the leading compartment at said floor next beyond and the following compartment at said one floor.

9. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said landing call registering means for causing operation of said mechanism to stop the leading compartment at the floors for which such landing calls are registered in the order of such floors; and means operable under conditions where with the car set for travel in said given direction calls are registered by said landing call registering means for a pair of adjacent floors for causing said leading compartment to pass the nearer of such adjacent floors and the car to be brought to a stop by said mechanism with the leading compartment at the farther of such floors and the following compartment at such nearer floor, regardless of the adjacent floors for which such calls are registered.

10. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to calls that are registered by said landing call registering means for causing operation of said mechanism to stop in the order of floors the leading compartment at the floors for which such landing calls are registered; and means responsive under conditions with the car set for travel in said given direction to a call registered by the car call registering means for the leading compartment or the landing call registering means for a floor next beyond one for which a call is registered by said landing call registering means for preventing operation of said mechanism to stop said leading compartment at said one floor and to cause operation of said mechanism to stop said leading compartment at said floor beyond and the following compartment at said one floor in response to such calls.

11. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to car calls registered by said car call registering means for the leading compartment for causing operation of said mechanism to stop in the order of floors said leading compartment at the floors for which such leading compartment car calls are registered; means responsive with the car set for travel in said given direction to landing calls registered by said landing call registering means for causing operation of said mechanism to stop in the order of floors said leading compartment at the floors for which such landing calls are registered; and means operable under conditions

where with the car set for travel in said given direction there is for a floor next beyond one for which a landing call is registered by said landing call registering means a call registered by said landing call registering means and/or by said leading compartment car call registering means for causing the leading compartment to pass said one floor and the car to be brought to a stop by said mechanism with the following compartment at such one floor and the leading compartment at such floor beyond to answer such calls for such floors.

10 12. In an elevator installation; a plurality of floors; an elevator car having a pair of superimposed compartments adapted to serve said floors; car actuating and stopping mechanism; a plurality of landing call registering means, one for each of said floors, for registering landing calls for a given direction of car travel; a plurality of car call registering means, one for each of said floors, for registering car calls for that one of said compartments which is leading when the car is travelling in said given direction; means responsive with the car set for travel in said given direction to car calls registered by said car call registering means for said leading compartment for causing operation of said mechanism to stop in the order of floors said leading compartment at the floors for which such leading compartment car calls are registered; means responsive with the car set for travel in said given direction to landing calls registered by said landing call registering means for causing operation of said mechanism to stop in the order of floors said leading compartment at the floors for which such landing calls are registered, regardless of the floors for which such landing calls are registered, provided that in each case there is not for a floor next beyond one for which such landing call is registered a landing call registered by said landing call registering means or a car call registered by said leading compartment car call registering means; and means operable under conditions where with the car set for travel in said given direction there is for a floor next beyond one for which a landing call is registered by said landing call registering means a call registered by said landing call registering means and/or by said leading compartment car call registering means for causing said leading compartment to pass such one floor and the car to be brought to a stop by said mechanism with the following compartment at such one floor and the leading compartment at such floor beyond in response to such calls.

13. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said landing call registering means for picking up such calls to cause operation of said mechanism to stop in the order of floors the following compartment at the floors for which such calls are registered; and means responsive with the car set for travel in said given direction to a call registered by said landing call registering means for a floor next preceding one for which a landing call is registered by said landing call registering means for causing operation of said mechanism to stop said following compartment at said preceding floor and the leading compartment at said one floor in response to such landing call for such one floor.

14. In an elevator installation; a plurality of floors; an elevator car having a pair of superimposed compartments adapted to serve said floors; car actuating and stopping mechanism; a plurality of landing call registering means, one for each of said floors; means responsive with the car set for travel in a given direction to calls that are registered by said landing call registering means for causing operation of said mechanism to stop in the order of floors the following compartment at the floors for which such landing calls are registered; and means operable under conditions where, with the car set for travel in said given

direction, calls are registered by said landing call registering means for a pair of adjacent floors for causing operation of said mechanism to stop said following compartment at the nearer of such adjacent floors and the leading compartment at the farther of such adjacent floors, regardless of the adjacent floors for which such calls are registered.

15. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to calls that are registered by said landing call registering means for causing operation of said mechanism to stop in the order of floors the following compartment at the floors for which such landing calls are registered; and means responsive under conditions with the car set for travel in said given direction to a call registered by the car call registering means for the following compartment or the landing call registering means for a floor next preceding one for which a call is registered by said landing call registering means for causing operation of said mechanism to stop said following compartment at said preceding floor and the leading compartment at said one floor in response to such calls.

16. In an elevator installation; a plurality of floors; an elevator car having a pair of superimposed compartments adapted to serve said floors; car actuating and stopping mechanism; a plurality of landing call registering means, one for each of said floors; a plurality of car call registering means, one for each of said floors, for each compartment; means responsive with the car set for travel in a given direction to car calls registered by said car call registering means for the following compartment for causing operation of said mechanism to stop in the order of floors said following compartment at the floors for which such following compartment car calls are registered; means responsive with the car set for travel in said given direction to landing calls registered by said landing call registering means for causing operation of said mechanism to stop in the order of floors said following compartment at the floors for which such landing calls are registered; and means operable under conditions where with the car set for travel in said given direction there is for a floor next preceding one for which a landing call is registered by said landing call registering means a call registered by said landing call registering means and/or by said following compartment car call registering means for causing the car to be brought to a stop by said mechanism with the leading compartment at such one floor and the following compartment at such preceding floor to answer such calls for such floors.

17. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; a plurality of call registering means, one for each of said floors, for registering car calls for that one of said compartments which is following when the car is travelling in said given direction; means responsive with the car set for travel in said given direction to car calls registered by said car call registering means for said following compartment for causing operation of said mechanism to stop in the order of floors said following compartment at the floors for which such following compartment car calls are registered; means responsive with the car set for travel in said given direction to landing calls registered by said landing call registering means for causing operation of said mechanism to stop in the order of floors said following compartment at the floors for which such landing calls are registered; and means operable under conditions where with the car

set for travel in said given direction there is for a floor next beyond one for which a landing call and/or a bottom compartment car call is registered a call registered by said landing call registering means for causing the leading compartment to answer such landing call for such floor next beyond at the same time that the following compartment is brought to a stop at such one floor in response to such call for such one floor.

18. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; a plurality of car call registering means, one for each of said floors, for each compartment; means responsive with the car set for travel in said given direction to landing calls registered by said landing call registering means for causing operation of said mechanism to stop in the order of floors the leading compartment at the floors for which such landing calls are registered; and means responsive under conditions with the car set for travel in said given direction to a car call registered by the following compartment call registering means for the same floor for which a landing call is registered by said landing call registering means for preventing operation of said mechanism to stop the leading compartment at said one floor and to cause operation of said mechanism to stop the following compartment at such one floor in response to such calls.
19. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; a plurality of call registering means, one for each of said floors, for registering car calls for that one of said compartments which is following when the car is travelling in said given direction; means responsive with the car set for travel in said given direction to landing calls registered by said landing call registering means for causing operation of said mechanism to stop in the order of floors the leading compartment at the floors for which such landing calls are registered, regardless of for which such floors such landing calls are registered, provided that in each case there is not for a floor next beyond one for which such landing call is registered a landing call registered by said landing call registering means or for such one floor a car call registered by said following compartment car call registering means; and means responsive under conditions with the car set for travel in said given direction to a car call registered by said following compartment call registering means for the same floor for which a landing call is registered by said landing call registering means for causing the leading compartment to pass by said one floor and the car to be brought to a stop by said mechanism with the following compartment at such one floor.
20. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; a plurality of call registering means, one for each of said floors, for registering car calls for that one of said compartments which is following when the car is travelling in said given direction; means responsive with the car set for travel in said given direction to car calls registered by said car call registering means for said following compartment for causing operation of said mechanism to stop in the order of floors said following compartment at the floors for which such following compartment car calls are registered; means responsive with the car set for travel in said given direction to landing calls registered by said landing call registering means for causing operation of said mech-

anism to stop in the order of floors the leading compartment at the floors for which such landing calls are registered, regardless of the floors for which such landing calls are registered, provided that in each case there is not for a floor next beyond one for which such landing call is registered a landing call registered by said landing call registering means or for such one floor a car call registered by said following compartment car call registering means; and means operable under conditions where with the car set for travel in said given direction there is for a floor next beyond one for which a landing call is registered by said landing call registering means a call registered by said landing call registering means and/or there is for such one floor a call registered by said following compartment car call registering means for causing the car to be brought to a stop by said mechanism with the following compartment at such one floor and the leading compartment at such floor beyond in response to such calls.

21. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors the leading compartment at the floors for which such up landing calls are registered, regardless of the floors for which such up landing calls are registered, provided that none of such registered up landing calls is for a floor next preceding one for which another up landing call is registered; means responsive with the car set for travel in the down direction to said down landing calls that are registered for causing operation of said mechanism to stop in the order of floors the leading compartment at the floors for which such down landing calls are registered, regardless of the floors for which such down landing calls are registered, provided that none of such registered down landing calls is for a floor next preceding one for which another down landing call is registered; and means operable under conditions where with the car set for travel in either direction a landing call for that direction is registered for a floor next preceding one for which another landing call for that direction is registered for modifying operation of said mechanism to cause it to stop the following compartment at such preceding floor and the leading compartment at such one floor in response to said landing calls for such preceding floor and such one floor.

22. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors said top compartment at the floors for which such up landing calls are registered, regardless of the floors for which such up landing calls are registered, provided that none of such registered up landing calls is for a floor next below one for which another up landing call is registered; means responsive with the car set for travel in the down direction to said down landing calls that are registered for causing operation of said mechanism to stop in the order of floors said bottom compartment at the floors for which such down landing calls are registered, regardless of the floors for which such down landing calls are registered, provided that none of such registered down landing calls is for a floor next above one for which another down landing call is

registered; means responsive under conditions with the car set for travel in the up direction to up landing calls registered for a pair of adjacent floors for modifying operation of said mechanism to cause it to stop the bottom compartment at the lower of such adjacent floors and the top compartment at the upper of such floors; and means responsive under conditions with the car set for travel in the down direction to down landing calls registered for a pair of adjacent floors for modifying operation of said mechanism to cause it to stop the top compartment at the upper of such adjacent floors and the bottom compartment at the lower of such floors.

23. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each of said floors, for each compartment; means responsive with the car set for travel in the up direction to said up landing calls and top compartment car calls that are registered for causing operation of said mechanism to stop in the order of floors said top compartment at the floors for which such up landing calls and top compartment car calls are registered; means responsive with the car set for travel in the down direction to said down landing calls and bottom compartment car calls that are registered for causing operation of said mechanism to stop in the order of floors said bottom compartment at the floors for which such down landing calls and bottom compartment car calls are registered; means responsive under conditions with the car set for travel in the up direction to an up landing call registered for the lower of a pair of adjacent floors and an up landing call or top compartment car call registered for the upper of such floors for modifying operation of said mechanism to cause it to stop the bottom compartment at the lower of such adjacent floors and the top compartment at the upper of such adjacent floors; and means responsive under conditions with the car set for travel in the down direction to a down landing call registered for the upper of a pair of adjacent floors and a down landing call or bottom compartment car call registered for the lower of such adjacent floors for modifying operation of said mechanism to cause it to stop the top compartment at the upper of such adjacent floors and the bottom compartment at the lower of such floors.

24. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each of said floors, for each compartment; means responsive with the car set for travel in the up direction to said up landing calls that are registered for causing operation of said mechanism to stop in the order of floors said top compartment at the floors for which such up landing calls are registered; means responsive with the car set for travel in the down direction to said down landing calls that are registered for causing operation of said mechanism to stop in the order of floors said bottom compartment at the floors for which such down landing calls are registered; means responsive with the car set for travel in said up direction to said bottom compartment car calls that are registered for causing operation of said mechanism to stop in the order of floors said bottom compartment at the floors for which said bottom compartment car calls are registered and where a bottom compartment car call is registered for the same floor as an up landing call is registered for preventing operation of said mechanism to stop the top compartment at such floor and to

cause it to stop the bottom compartment at such floor to answer such up landing call; and means responsive with the car set for travel in said down direction to said top compartment car calls that are registered for causing operation of said mechanism to stop in the order of floors said top compartment at the floors for which said top compartment car calls are registered and where a top compartment car call is registered for the same floor as a down landing call is registered for preventing operation of said mechanism to stop the bottom compartment at such floor and to cause it to stop the top compartment at such floor to answer such down landing call.

25. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each of said floors, for each compartment; means responsive with the car set for travel in the up direction to said up landing calls and top compartment car calls that are registered for causing operation of said mechanism to stop in the order of floors said top compartment at the floors for which such up landing calls and top compartment car calls are registered; means responsive with the car set for travel in said up direction to said bottom compartment car calls that are registered for causing operation of said mechanism to stop in the order of floors said bottom compartment at the floors for which such up landing calls and top compartment car calls are registered; means responsive with the car set for travel in the down direction to said down landing calls and bottom compartment car calls that are registered for causing operation of said mechanism to stop in the order of floors said bottom compartment at the floors for which such down landing calls and bottom compartment car calls are registered; means responsive with the car set for travel in said down direction to said top compartment car calls that are registered for causing operation of said mechanism to stop in the order of floors said top compartment at the floors for which said top compartment car calls are registered; means responsive under conditions with the car set for travel in the up direction to an up landing call registered for the lower of a pair of adjacent floors and a bottom compartment car call registered for the lower of such floors or a top compartment car call registered for the upper of such floors for modifying operation of said mechanism to prevent its stopping the top compartment at the lower of such floors and to cause it to stop the bottom compartment at the lower of such floors and the top compartment at the upper of such floors; and means responsive under conditions with the car set for travel in the down direction to a down landing call registered for the upper of a pair of adjacent floors and a top compartment car call registered for the upper of such floors or a bottom compartment car call registered for the lower of such floors for modifying operation of said mechanism to prevent its stopping the bottom compartment at the upper of such floors and to cause it to stop the top compartment at the upper of such floors and the bottom compartment at the lower of such floors.

26. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors the following compartment at the floors for which such up landing calls are registered; means responsive with the car set for travel in the down direction to said down

landing calls that are registered for causing operation of said mechanism to stop in the order of floors the leading compartment at the floors for which such down landing calls are registered, regardless of the floors for which such down landing calls are registered, provided that none of such registered down landing calls is for a floor next beyond one for which another down landing call is registered; and means operable under conditions where with the car set for travel in either direction a landing call for that direction is registered for a floor next beyond one for which another landing call for that direction is registered for modifying operation of said mechanism to cause it to stop the leading compartment at such floor beyond and the following compartment at such one floor in response to said calls for such floors.

27. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors said bottom compartment at the floors for which such up landing calls are registered; means responsive with the car set for travel in the down direction to said down landing calls that are registered for causing operation of said mechanism to stop in the order of floors said top compartment at the floors for which such down landing calls are registered; means responsive under conditions with the car set for travel in the up direction to up landing calls registered for a pair of adjacent floors for modifying operation of said mechanism to cause it to stop the bottom compartment at the lower of such floors and the top compartment at the upper of such floors to answer such up landing calls; and means responsive under conditions with the car set for travel in the down direction to down landing calls registered for a pair of adjacent floors for modifying operation of said mechanism to cause it to stop the top compartment at the upper of such floors and the bottom compartment at the lower of such floors to answer such down landing calls.

28. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in the up direction to said up landing calls and bottom compartment car calls that are registered for causing operation of said mechanism to stop in the order of floors said bottom compartment at the floors for which such up landing calls and bottom compartment car calls are registered; means responsive with the car set for travel in the down direction to said down landing calls and top compartment car calls that are registered for causing operation of said mechanism to stop in the order of floors said top compartment at the floors for which such down landing calls and top compartment car calls are registered; means responsive under conditions with the car set for travel in the up direction to an up landing call registered for the upper of a pair of adjacent floors and a bottom compartment car call registered for the lower of such floors for modifying operation of said mechanism to cause it to stop the bottom compartment at the lower of such floors to answer the bottom compartment car call for that floor and the top compartment at the upper of such floors to answer such up landing call; and means responsive under conditions

with the car set for travel in the down direction to a down landing call registered for the lower of a pair of adjacent floors and a top compartment car call registered for the upper of such floors for modifying operation of said mechanism to cause it to stop the top compartment at the upper of such floors to answer the top compartment car call for that floor and the bottom compartment at the lower of such floors to answer such down landing call.

29. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in the up direction to said up landing calls that are registered for causing operation of said mechanism to stop in the order of floors said bottom compartment at the floors for which such up landing calls are registered; means responsive with the car set for travel in the down direction to said down landing calls that are registered for causing operation of said mechanism to stop in the order of floors said top compartment at the floors for which such down landing calls are registered; means responsive with the car set for travel in said up direction to said top compartment car calls that are registered for causing operation of said mechanism to stop in the order of floors said top compartment at the floors for which said top compartment car calls are registered and where a top compartment car call is registered for the same floor as an up landing call is registered for causing operation of said mechanism to stop the top compartment at such floor to answer such up landing calls for that floor; and means responsive with the car set for travel in said down direction to said bottom compartment car calls that are registered for causing operation of said mechanism to stop in the order of floors said bottom compartment at the floors for which said bottom compartment car calls are registered and where a bottom compartment car call is registered for the same floor as a down landing call is registered for causing operation of said mechanism to stop the bottom compartment at such floor to answer such down landing call for that floor.

30. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in the up direction to said up landing calls and bottom compartment car calls that are registered for causing operation of said mechanism to stop in the order of floors said bottom compartment at the floors for which such up landing calls and bottom compartment car calls are registered; means responsive with the car set for travel in said up direction to said top compartment car calls that are registered for causing operation of said mechanism to stop in the order of floors said top compartment at the floors for which said top compartment car calls are registered; means responsive with the car set for travel in the down direction to said down landing calls and top compartment car calls that are registered for causing operation of said mechanism to stop in the order of floors said top compartment at the floors for which such down landing calls and top compartment car calls are registered; means responsive with the car set for travel in said down direction to said bottom compartment car calls that are registered

for causing operation of said mechanism to stop in the order of floors said bottom compartment at the floors for which said bottom compartment car calls are registered; means responsive under conditions with the car set for travel in the up direction to an up landing call registered for the upper of a pair of adjacent floors and a bottom compartment car call registered for the lower of such floors or a top compartment car call registered for the upper of such floors for modifying operation of said mechanism to cause it to stop the bottom compartment at the lower of such floors to answer the bottom compartment car call for that floor if registered and the top compartment at the upper of such floors to answer such up landing call and if registered the top compartment car call for that floor; and means responsive under conditions with the car set for travel in the down direction to a down landing call registered for the lower of a pair of adjacent floors and a top compartment car call registered for the upper of such floors or a bottom compartment car call registered for the lower of such floors for modifying operation of said mechanism to cause it to stop the top compartment at the upper of such floors to answer the top compartment car call for that floor if registered and the bottom compartment at the lower of such floors to answer such down landing call and if registered the bottom compartment car call for that floor.

31. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each closure means; stopping means responsive with the car set for travel in said given direction to said landing calls that are registered for causing operation of said mechanism to stop in the order of floors the following compartment at the floors for which such landing calls are registered and operation of said closure operating means for that compartment to open said closure means for that compartment as each of such stops is made; and means controlled, under conditions where with the car set for travel in said given direction a landing call is registered by said landing call registering means for a floor next beyond one for which another landing call is registered by said landing call registering means, by the response of said stopping means to effect the stopping of said following compartment at such floor for which such other call is registered for causing in response to such call for said floor next beyond operation of said closure operating means for the leading compartment to open said closure means for that compartment as that compartment comes to a stop at such floor next beyond.

32. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each closure means; a plurality of hall lanterns, one for each of said floors, for said given direction of travel; stopping means responsive with the car set for travel in said given direction to said landing calls that are registered for causing operation of said mechanism to stop in the order of floors the following compartment at the floors for which such landing calls are registered, lighting of said hall lanterns for such floors, and operation of said closure operating means for that compartment to open said closure means for that compartment as each of such stops is made; and means responsive, under conditions where with the car set for travel in said given direction a landing call is registered by said landing call registering means for a floor next

beyond one for which another landing call is registered by said landing call registering means, for causing, incident to the initiation of the stopping of said following compartment at said one floor for which such other landing call is registered, lighting of said hall lantern for such next beyond floor and operation of said closure operating means for the leading compartment to open said closure means for that compartment as the compartments come to a stop at such floors.

33. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each closure means; stopping means responsive with the car set for travel in said given direction to said landing calls that are registered for causing operation of said mechanism to stop in the order of floors the leading compartment at the floors for which such landing calls are registered and operation of said closure operating means for that compartment to open said closure means for that compartment as each of such stops is made, regardless of the floors for which such landing calls are registered, provided that none of such registered landing calls is for a floor next preceding one for which another landing call is registered; and means responsive, under conditions where with the car set for travel in said given direction a landing call is registered by said landing call registering means for a floor next preceding one for which another landing call is registered by said landing call registering means, to said landing call for such other floor for causing said leading compartment to pass said next preceding floor and thereafter responsive to said landing calls for such other floor and next preceding floor for causing operation of said mechanism to stop the car with said leading compartment at such other floor and the following compartment at such preceding floor and operation of said closure operating means for both compartments to open said closure means for those compartments as the compartments come to a stop at such floors.

34. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each closure means; a plurality of hall lanterns, one for each of said floors, for said given direction of travel; stopping means responsive with the car set for travel in said given direction to said landing calls that are registered for causing operation of said mechanism to stop in the order of floors the leading compartment at the floors for which such landing calls are registered, lighting of said hall lanterns for such floors, and operation of said closure operating means for that compartment to open said closure means for that compartment as each of such stops is made, regardless of the floors for which such landing calls are registered, provided that none of such registered landing calls is for a floor next preceding one for which another landing call is registered; and means responsive, under conditions where with the car set for travel in said given direction a landing call is registered by said landing call registering means for a floor next preceding one for which another landing call is registered by said landing call registering means, to said landing call for such other floor for causing said leading compartment to pass said next preceding floor and thereafter responsive to said landing calls for such other and next preceding floors for causing operation of said mechanism to stop the car with said leading compartment at such other floor and the following compartment at such preceding floor, lighting of said

hall lanterns for such floors, and operation of said closure operating means for both compartments to open said closure means for those compartments as the compartments come to a stop at such floors.

- 5 35. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop at the floors for which such up landing calls are registered, in the order of floors, a certain one of said compartments; means responsive with the car set for travel in the down direction to said down landing calls that are registered for causing operation of said mechanism to stop at the floors for which such down landing calls are registered, in the order of such floors, the same one of said compartments that was stopped during the up trip at the floors for which such up landing calls were registered; and means responsive with the car set for travel in either direction to landing calls for that direction that are registered for a pair of adjacent floors for causing operation of said mechanism to stop the leading compartment at the farther of such adjacent floors and the following compartment at the nearer of such adjacent floors, whereby but one stop is made in answering such calls.

- 30 36. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors a certain one of said compartments at the floors for which such up landing calls are registered; means responsive with the car set for travel in the down direction to said down landing calls that are registered for causing operation of said mechanism to stop in the order of floors said certain one of said compartments at the floors for which such down landing calls are registered; means responsive with the car set for travel in the up direction to up landing calls that are registered for a pair of adjacent floors for causing operation of said mechanism to stop the top compartment at the higher of such adjacent floors and the bottom compartment at the lower of such adjacent floors; and means responsive with the car set for travel in said down direction to down landing calls that are registered for a pair of adjacent floors for causing operation of said mechanism to stop the bottom compartment at the lower of such adjacent floors and the top compartment at the higher of such adjacent floors, regardless of which of said compartments is said certain one which answers the landing calls where landing calls for adjacent floors are not involved.

37. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in a given direction to said landing calls for that direction that are registered for causing operation of said mechanism to stop in the order of floors a certain one of said compartments at the floors for which such landing calls for that direction are registered; means responsive with the car set for travel in said given direction to a landing call for the opposite direction that is registered for causing operation of said mechanism

to stop the leading compartment at the floor for which such landing call for said opposite direction is registered, provided a landing call for said given direction for such floor or floor next preceding, or a landing call for a floor beyond is not registered; and means responsive with the car set for travel in said given direction to landing calls for the opposite direction that are registered for a pair of adjacent floors for causing operation of said mechanism to stop the leading compartment at the farther of such adjacent floors and the following compartment at the nearer of such adjacent floors in response to such calls, provided a landing call for said given direction is not registered for either of such adjacent floors or a landing call is not registered for a floor beyond such adjacent floors.

38. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors a certain one of said compartments at the floors for which such up landing calls are registered; means responsive with the car set for travel in the up direction to a down landing call that is registered for causing operation of said mechanism to stop the leading compartment at the floor for which such down landing call is registered, provided an up landing call for such floor, an up landing call for the floor next below, or landing call for a floor above is not registered; and means responsive to a down landing call for a floor next below the one for which said response to a down landing call is being made for causing the following compartment to answer said down landing call for said floor next below.

39. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to said up landing calls that are registered for causing operation of said mechanism to stop in the order of floors said top compartment at the floors for which such up landing calls are registered, regardless of the floors for which such up landing calls are registered, provided they are not for adjacent floors; means responsive with the car set for travel in the up direction to a down landing call that is registered for causing operation of said mechanism to stop the top compartment at the floor for which such down landing call is registered, provided no call is registered indicating travel of the car beyond such floors; means responsive with the car set for travel in the up direction to a down landing call for a floor next below one for which a top compartment car call is registered under conditions where such calls are the highest calls for causing the bottom compartment to answer such down landing call for said floor next below at the same time that the top compartment answers such car call; and means responsive to the answering of a down call on an up trip for causing the car to be set for travel in the down direction as the stop is made.

40. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in a given direction to car calls for

the leading compartment that are registered for causing operation of said mechanism to stop in the order of floors the leading compartment at the floors for which such car calls are registered; means responsive with the car set for travel in a given direction to said landing calls for that direction that are registered for causing operation of said mechanism to stop in the order of floors a certain one of said compartments at the floors for which such landing calls for that direction are registered, and means responsive with the car set for travel in said given direction to a landing call for the opposite direction that is registered for a floor next preceding one for which a leading compartment car call is registered under conditions where such calls are the farthest calls in said given direction for causing the following compartment to answer said landing call for said opposite direction upon operation of said mechanism to stop the leading compartment at the floor for which such car call is registered.

41. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each floor, for each compartment for registering car calls for that compartment; means responsive with the car set for travel in the up direction to car calls that are registered for causing operation of said mechanism to stop the respective compartments for which such car calls are registered at the floors for which such car calls are registered; means responsive with the car set for travel in the up direction to said up landing calls that are registered for causing operation of said mechanism to stop in the order of floors said top compartment at the floors for which such up landing calls are registered, regardless of the floors for which such up landing calls are registered, provided they are not for adjacent floors; means responsive with the car set for travel in the up direction to a down landing call that is registered for causing operation of said mechanism to stop the top compartment at the floor for which such down landing call is registered, provided no call is registered indicating travel of the car beyond such floors; means responsive with the car set for travel in the up direction to a down landing call for a floor next below one for which a top compartment car call is registered under conditions where such calls are the highest calls for causing the bottom compartment to answer such down landing call for said floor next below at the same time that the top compartment answers such car call; and means responsive to the answering of the last named down call and top compartment car call for causing the car to be set for travel in the down direction as the stop is made.

42. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each of said floors, for each compartment; means responsive with the car set for travel in the up direction to car calls for each compartment that are registered for causing operation of said mechanism to stop in the order of floors that compartment at the floors for which such car calls for that compartment are registered; means responsive with the car set for travel in the up direction to said up landing calls that are registered for causing operation of said mechanism to stop in the order of floors a certain one of said compartments at the floors for which such up landing calls are registered; and means operable under conditions where with the car set for travel in said up direction there is a down landing call in registration for a floor next above

one for which a following compartment car call is registered and where such calls are the highest calls for modifying operation of said mechanism to cause it to stop the leading compartment at the floor for which such down landing call is registered to answer such call at the same time that the bottom compartment is stopped to answer such car call, regardless of which compartment is said certain one.

43. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in the up direction to car calls for each compartment that are registered for causing operation of said mechanism to stop in the order of floors that compartment at the floors for which such car calls for that compartment are registered; means responsive with the car set for travel in the up direction to said up landing calls that are registered for causing operation of said mechanism to stop in the order of floors a certain one of said compartments at the floors for which such up landing calls are registered; and means operable under conditions where with the car set for travel in said up direction there is a down landing call in registration for the same floor for which a following compartment car call is registered and where such calls are the highest calls for causing, upon operation of said mechanism to stop the following compartment at the floor for which such following compartment car call is registered, the following compartment to answer such down landing call at the same time, regardless of which compartment is said certain one.

44. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; a plurality of car call registering means, one for each of said floors, for each compartment; means responsive with the car set for travel in the up direction to car calls for each compartment that are registered for causing operation of said mechanism to stop in the order of floors that compartment at the floors for which such car calls for that compartment are registered; means responsive with the car set for travel in the up direction to said up landing calls for that direction that are registered for causing operation of said mechanism to stop in the order of floors a certain one of said compartments at the floors for which such up landing calls are registered; means responsive with the car set for travel in the up direction to a down landing call that is registered for causing operation of said mechanism to stop the leading compartment at the floor for which such down landing call is registered, provided such call is the highest call; and means operable under conditions where with the car set for travel in said up direction there is a following compartment car call in registration for the same floor for which such down landing call is registered and where such calls are the highest calls for modifying operation of said mechanism to cause said leading compartment to bypass such down landing call and to cause, upon operation of said mechanism, to stop the following compartment at the floor for which such following compartment car call is registered, the following compartment to answer such down landing call at the same time.

45. In an elevator installation; a plurality of floors; an elevator car having a top compartment and a bottom

compartment adapted to serve said floors; car actuating and stopping mechanism; a plurality of call registering means, one for each of said floors, for registering up landing calls; a plurality of call registering means, one for each of said floors, for registering down landing calls; a plurality of call registering means, one for each of said floors, for each compartment for registering car calls for that compartment; means responsive with the car set for travel in the up direction to car calls for each compartment that are registered for causing operation of said mechanism to stop in the order of floors that compartment at the floors for which such car calls for that compartment are registered; means responsive with the car set for travel in the up direction to said up landing calls for that direction that are registered for causing operation of said mechanism to stop in the order of floors the top compartment at the floors for which such up landing calls are registered, regardless of the floors for which such up landing calls are registered, provided they are not for adjacent floors; means responsive with the car set for travel in the up direction to a down landing call that is registered for causing operation of said mechanism to stop the top compartment at the floor for which such down landing call is registered, provided such call is the highest call; means operable under conditions where with the car set for travel in said up direction there is a following compartment car call in registration for the same floor for which such down landing call is registered and where such calls are the highest calls for modifying operation of said mechanism to prevent said top compartment answering such down landing call and to stop the bottom compartment at the floor for which such bottom compartment car call and down landing call are registered in answer to such calls; and means responsive to the answering of such down landing call on an up trip for setting the car for travel in the down direction as the stop is made.

46. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in either direction to landing calls for that direction that are registered for causing operation of said mechanism to stop in the order of floors the leading compartment at the floors for which such landing calls for that direction are registered; and means operable under conditions where any such landing call is registered too late to be answered by the leading compartment but in time to be answered by the following compartment for causing operation of said mechanism to stop the following compartment at the floor for which such late landing call is registered in response to such late landing call, regardless of the floor for which such late landing call is registered.

47. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to up landing calls that are registered for causing operation of said mechanism to stop in the order of floors the top compartment at the floors for which such up landing calls are registered; means responsive with the car set for travel in the down direction to down landing calls that are registered for causing operation of said mechanism to stop in the order of floors the bottom compartment at the floors for which such down landing calls are registered; means operable under conditions where during an up trip an up landing call is

registered too late to be answered by the top compartment but in time to be answered by the bottom compartment for causing operation of said mechanism to stop the bottom compartment at the floor for which such late up landing call is registered in response to such late up landing call, regardless of the floor for which such late up landing call is registered; and means operable under conditions where during a down trip a down landing call is registered too late to be answered by the bottom compartment but in time to be answered by the top compartment for causing operation of said mechanism to stop the top compartment at the floor for which such late down landing call is registered in response to such late down landing call, regardless of the floor for which such late down landing call is registered.

48. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; means responsive with the car set for travel in said given direction to said landing calls that are registered for causing operation of said mechanism to stop in the order of floors a certain one of said compartments at the floors for which such landing calls are registered; means for said certain one of said compartments operable in response to a certain load in that compartment for preventing stopping of that compartment during travel in said given direction at floors for which said landing calls are registered; and means controlled by said load responsive means and adapted upon said operation thereof during travel in said given direction to cause operation of said mechanism to stop the other of said compartments at the floors for which said landing calls are registered in response to such calls.

49. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; means responsive with the car set for travel in said given direction to said landing calls that are registered for causing operation of said mechanism to stop in the order of floors a certain one of said compartments at the floors for which such landing calls are registered; a load weighing switch for each compartment operable upon that compartment taking on a certain load; means for each compartment responsive to operation of said load weighing switch for that compartment for preventing stopping of that compartment at floors for which landing calls are registered; and means responsive during car travel in said given direction to operation of said load weighing switch for said certain one of said compartments for rendering said mechanism effective to cause stopping of the other compartment at the floors for which said landing calls are registered in response to such calls, provided said load weighing switch for said other compartment is not operated.

50. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in either direction to landing calls for that direction that are registered for causing operation of said mechanism to stop in the order of floors the following compartment at the floors for which such landing calls are registered; means for each compartment responsive to a certain load in that compartment for preventing stopping of that compartment during car travel in either direction at floors for which landing calls for that direction are registered; and means responsive during car travel in either direction to oper-

ation of said load responsive means for the following compartment for that direction for rendering said mechanism effective to cause stopping of the leading compartment during such car travel in that direction at the floors for which landing calls for that direction are registered in response to such calls.

51. In an elevator installation; a plurality of floors; an elevator car having a pair of superimposed compartments adapted to serve said floors; car actuating and stopping mechanism; a plurality of call registering means, one for each of said floors, for registering up landing calls; a plurality of call registering means, one for each of said floors, for registering down landing calls; means responsive with the car set for travel in either direction to landing calls for that direction that are registered for causing operation of said mechanism to stop in the order of floors the leading compartment at the floors for which such landing calls are registered; means for each compartment responsive to a certain load in that compartment for preventing stopping of that compartment during car travel in either direction at floors for which landing calls for that direction are registered to bypass such calls; and means responsive during car travel in either direction to operation of said load responsive means for the leading compartment for that direction in effecting such automatic bypassing of landing calls for that direction by such leading compartment for rendering said mechanism effective to cause stopping of the following compartment during such car travel in that direction at the floors for which landing calls for that direction are registered in response to such calls.

52. In an elevator installation; a plurality of floors; an elevator car having a top compartment and a bottom compartment adapted to serve said floors; car actuating and stopping mechanism; a plurality of call registering means, one for each of said floors, for registering up landing calls; a plurality of call registering means, one for each of said floors, for registering down landing calls; means responsive with the car set for travel in the up direction to up landing calls that are registered for causing operation of said mechanism to stop in the order of floors the top compartment at the floors for which such up landing calls are registered; means responsive with the car set for travel in the down direction to down landing calls that are registered for causing operation of said mechanism to stop in the order of floors the bottom compartment at the floors for which such down landing calls are registered; means for the top compartment responsive to a certain load in that compartment for preventing stopping of that compartment during up car travel at floors for which up landing calls are registered to bypass such calls; means responsive to operation of said top compartment load responsive means in effecting such top compartment automatic bypassing of up landing calls for rendering said mechanism effective to cause stopping of the bottom compartment during such up car travel at the floors for which such top compartment bypassed up landing calls are registered in response to such calls; means for the bottom compartment responsive to a certain load in that compartment for preventing stopping of that compartment during down car travel at floors for which down landing calls are registered to bypass such calls; and means responsive to operation of said bottom compartment load responsive means in effecting such bottom compartment automatic bypassing of down landing calls for rendering said mechanism effective to cause stopping of the top compartment during such down car travel at the floors for which such bottom compartment bypassed down landing calls are registered in response to such calls.

53. In an elevator installation; a plurality of floors; an elevator car having a pair of superimposed compartments adapted to serve said floors; car actuating and stopping mechanism; a plurality of call registering means, one for each of said floors, for registering landing calls for a

given direction of car travel; means responsive with the car set for travel in said given direction to said landing calls for even numbered floors that are registered for causing operation of said mechanism to stop in the order of floors a certain one of said compartments at the floors for which such even numbered floor landing calls are registered, and to said landing calls for odd numbered floors that are registered for causing operation of said mechanism to stop in the order of floors the other compartment at the floors for which such odd numbered floor landing calls are registered; means for each of said compartments operable in response to a certain load in that compartment for preventing stopping of that compartment during travel in said given direction at floors for which said landing calls are registered; means controlled by said load responsive means for said one compartment and adapted upon said operation thereof during travel of the car in said given direction to cause operation of said mechanism to stop said other compartment at the even numbered floors for which said landing calls are registered in response to such calls; and means controlled by said load responsive means for said other compartment and adapted upon said operation thereof during travel of the car in said given direction to cause operation of said mechanism to stop said one compartment at the odd numbered floors for which said landing calls are registered in response to such calls.

54. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; means responsive with the car set for travel in said given direction to said landing calls for even numbered floors that are registered for causing operation of said mechanism to stop in the order of floors a certain one of said compartments at the floors for which such even numbered floor landing calls are registered; means responsive with the car set for travel in said given direction to said landing calls for odd numbered floors that are registered for causing operation of said mechanism to stop in the order of floors the other compartment at the floors for which such odd numbered floor landing calls are registered; a load weighing switch for each compartment operable upon that compartment taking on a certain load; means for each compartment operable in response to operation of said load weighing switch for that compartment for preventing stopping of that compartment during travel in said given direction at floors for which said landing calls are registered; means also operable in response to operation of said load weighing switch for said one compartment during travel of the car in said given direction to cause operation of said mechanism to stop said other compartment at all of said floors for which said landing calls are registered in response to such calls provided said load weighing switch for said other compartment is not operated; and means also operable in response to operation of said load weighing switch for said other compartment during travel of the car in said given direction to cause operation of said mechanism to stop said one compartment at all of said floors for which said landing calls are registered in response to such calls, provided said load weighing switch for said one compartment is not operated.

55. In an elevator installation; an elevator car serving a plurality of floors, said floors including an upper lobby floor and a lower lobby floor which form the lower terminal, said elevator car having a top compartment and a bottom compartment, the top compartment being positioned at the upper lobby floor and the bottom compartment being positioned at the lower lobby floor when the car is at the lower terminal; load weighing means for the top compartment operable when the load in that compartment is at or above a certain value; call registering means for the upper lobby floor for registering an up

landing call for such floor; car actuating and stopping mechanism operable during travel of said car in the up direction from the lower terminal to stop the bottom compartment at the upper lobby floor in response to said up landing call; means for preventing such operation of said car actuating and stopping mechanism to effect such stop; and means responsive to operation of said top compartment load weighing means for rendering said preventing means ineffective and thus said car actuating and stopping mechanism effective to stop the bottom compartment at the upper lobby floor in response to said call.

56. In an elevator installation; an elevator car serving a plurality of floors, said floors including an upper lobby floor and a lower lobby floor which form the lower terminal, said elevator car having a top compartment and a bottom compartment, the top compartment being positioned at the upper lobby floor and the bottom compartment being positioned at the lower lobby floor when the car is at the lower terminal; car actuating and stopping mechanism; load weighing means for the top compartment operable when the load in that compartment is at or above a certain value; call registering means for the bottom compartment for registering a car call for the upper lobby floor; means responsive to said registered car call for causing, during travel of said car in the up direction from the lower terminal, operation of said car actuating and stopping mechanism to stop the bottom compartment at the upper lobby floor; and means responsive to operation of said top compartment load weighing means for preventing such response to said car call under conditions where the load in the top compartment is below said certain value.

57. In an elevator installation in which a plurality of elevator cars serves a plurality of floors including an upper lobby floor and a lower lobby floor, each elevator car having a top compartment and a bottom compartment, the top compartment being positioned at the upper lobby floor and the bottom compartment being positioned at the lower lobby floor as a lower terminal for the car, in which mechanism is provided for selecting and dispatching the cars from the lower terminal, in which means are also provided for registering the availability of the cars at the lower terminal for selection for dispatching by said selecting and dispatching mechanism, in which car actuating and stopping mechanism is provided for each car, in which load weighing means are provided for the top compartment of each car which are operable when the load in that compartment is at or above a certain value, and in which call registering means are provided for the upper lobby floor for registering an up landing call for such floor; means responsive to said registered up landing call for said upper lobby floor for causing, upon dispatching of a car from the lower terminal in the up direction by said selecting and dispatching mechanism, operation of said car actuating and stopping mechanism for that car to stop the bottom compartment of that car at the upper lobby floor; and means controlled by said top compartment load weighing means for such dispatched car and by said availability registering means for preventing such response to said up landing call under conditions where the top compartment of such car has less than said certain load and another car is available at the lower terminal for selection for dispatching.

58. In an elevator installation in which a plurality of elevator cars serves a plurality of floors, said floors including an upper lobby floor and a lower lobby floor which are the lower terminal, each elevator car having a top compartment and a bottom compartment, the top compartment being positioned at the upper lobby floor and the bottom compartment being positioned at the lower lobby floor when that car is at the lower terminal, in which means are provided for registering the availability of the cars at the lower terminal for selection for dispatching by selecting and dispatching mechanism, in

which car actuating and stopping mechanism is provided for each car, in which load weighing means are provided for the top compartment of each car which are operable when the load in that compartment is at or above a certain value, and in which landing call registering means are provided for the upper lobby floor for registering an up landing call for such floor; means for preventing, during travel of a car in the up direction from the lower terminal, operation of said car actuating and stopping mechanism for that car to stop the bottom compartment of that car at the upper lobby floor in response to said up landing call; and means responsive to operation of said top compartment load weighing means for such car and said availability registering means for rendering said preventing means ineffective and for rendering said car actuating and stopping mechanism for such car operable to stop the bottom compartment of such car at the upper lobby floor in response to said up landing call for said upper lobby floor, under conditions where the load in the top compartment of such car is at or above said certain value and another car is available at the lower terminal for selection for dispatching.

59. In an elevator installation in which a plurality of elevator cars serves a plurality of floors, said floors including an upper lobby floor and a lower lobby floor which are the lower terminal, each elevator car having a top compartment and a bottom compartment, the top compartment being positioned at the upper lobby floor and the bottom compartment being positioned at the lower lobby floor when that car is at the lower terminal, in which car actuating and stopping mechanism is provided for each car, in which load weighing means are provided for the top compartment of each car which are operable when the load in that compartment at the upper lobby floor is at or above a certain value, and in which landing call registering means are provided for the upper lobby floor for registering an up landing call for such floor; means for preventing, during travel of a car in the up direction from the lower terminal, operation of said car actuating and stopping mechanism for that car to stop the bottom compartment of that car at the upper lobby floor in response to said up landing call; and means responsive to operation of said top compartment load weighing means for such car and said availability registering means for rendering said preventing means ineffective and for rendering said car actuating and stopping mechanism for such car operable to stop the bottom compartment of such car at the upper lobby floor in response to said up landing call for said upper lobby floor, under conditions where the load in the top compartment of such car and the load in the top compartment of another up travelling car, acquired at the upper lobby, is at or above said certain value.

60. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable when the closure means for that compartment are opened with that compartment stopped at a floor to provide a closure time interval upon the expiration of which such closure means are closed by said closure operating means for that compartment; and means for each compartment operable, when the closure means for both compartments are open which the compartments stopped at adjacent floors during travel of the car in said given direction, upon the registering and maintaining registered of said landing call for either of such floors to maintain open said closure means for both of said compartments.

61. In an elevator installation; a plurality of floors; an elevator car having a pair of superimposed comp-

ments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable when the closure means for that compartment are opened with that compartment stopped at a floor to provide a closure time interval upon the expiration of which such closure means are closed by said closure operating means for that compartment; and means for each compartment operable, when the closure means for that compartment are open with that compartment stopped at a floor to provide a closure time interval upon the expiration of which such closure means are closed by said closure operating means for that compartment; and means for each compartment operable, when the closure means for that compartment are open with that compartment stopped at a floor during travel of the car in said given direction, upon the registering and maintaining registered of said landing call for that floor to prevent closure of such closure means upon expiration of said closure time interval for that compartment and operable, when the closure means for both compartments are open with the compartments stopped at adjacent floors during travel of the car in said given direction, upon the registering and maintaining registered of said landing call for the floor at which that compartment is stopped to prevent closure of said closure means for both of said compartments upon expiration of said closure time interval for that compartment.

62. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable when the closure means for that compartment are opened with that compartment stopped at a floor to provide a closure time interval upon the expiration of which such closure means are closed by said closure operating means for that compartment; means for each compartment operable, when the closure means for that compartment are open with that compartment stopped at a floor during travel of the car in said given direction, upon the registering and maintaining registered of said landing call for that floor to prevent closure of such closure means upon expiration of said closure time interval for that compartment; means for each compartment operable, when the closure means for both compartments are open with the compartments stopped at adjacent floors during travel of the car in said given direction, upon the registering and maintaining registered of said landing call for either of such floors to prevent closure of said closure means for both of said compartments upon expiration of said closure time interval for that compartment; and means for rendering said preventing means ineffective upon expiration of a certain time interval after the stop is made.

63. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; stopping means responsive with the car set for travel in said given direction to said registered landing calls for adjacent floors for causing operation of said mechanism to stop the leading compartment at the farther one of such floors and the following compartment at the nearer one of such floors; closure control means for each compartment operable incident to the stopping of that compartment at a floor in response to said landing call for that floor for causing operation of said closure operating means for that compartment to open said closure means for that compartment as such stop

is made, said closure control means for each compartment acting upon such answering of a call by that compartment to cause after expiration of a certain time interval operation of said closure operating means for that compartment to close said closure means for that compartment; transfer time means for each compartment operable incident to the stopping of that compartment to provide a passenger transfer time interval for that compartment, said call registering means for either of such floors at which the compartments are stopped with their closure means open being effective if actuated and maintained actuated to delay the running of said certain time interval for that compartment until expiration of said transfer time interval for that compartment; and means for preventing operation of said closure operating means for either compartment to close said closure means for that compartment under conditions where the closure means for the other compartment are being maintained open as a result of such maintaining actuated of said call registering means for the floor at which the other compartment is stopped until the expiration of said certain time interval for such other compartment.

64. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; stopping means responsive with the car set for travel in said given direction to a registered one of said landing calls for causing operation of said mechanism to stop a certain one of said compartments at the floor for which such landing call is registered; closure control means for each compartment operable incident to the stopping of that compartment at a floor in response to said call for that floor for causing operation of said closure operating means for that compartment to open said closure means for that compartment as such stop is made, said closure control means for each compartment acting upon such answering of a call by that compartment to cause after expiration of a certain time interval operation of said closure operating means for that compartment to close said closure means for that compartment; transfer time means for each compartment operable incident to the stopping of that compartment to provide a passenger transfer time interval for that compartment, said closure control means for a compartment, other than the one which is being stopped or has been stopped at a floor in response to said landing call for that floor, being responsive to the late registration of said landing call for the floor at which such other compartment has been or is being stopped, but before expiration of the passenger transfer time interval for such other compartment for causing operation of said closure operating means for such other compartment to open the closure means for such other compartment, and said call registering means for either of such floors at which the compartments are stopped with their closure means open being effective if actuated and maintained actuated to delay the running of said certain time interval for the compartment stopped at that floor until expiration of said transfer time interval for that compartment; and means for preventing operation of said closure operating means for either compartment to close said closure means for that compartment under conditions where the closure means for the other compartment are being maintained open as a result of such maintaining actuated of said call registering means for the floor at which the other compartment is stopped until the expiration of said certain time interval for such other compartment.

65. In an elevator installation; a plurality of floors;

- an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable when the closure means for that compartment are opened with that compartment stopped at a floor to provide a closure time interval upon the expiration of which such closure means are closed by said closure operating means for that compartment; means for each compartment operable, when the closure means for that compartment are open with that compartment stopped at a floor during travel of the car in said given direction, upon the registering and maintaining registered of said landing call for that floor before expiration of a certain time interval after the stop is made to prevent closure of such closure means by said closure operating means for that compartment; and means for each compartment operable, when the closure means for both compartments are open with the compartments stopped at adjacent floors during travel of the car in said given direction, upon the registering and maintaining registered of said landing call for either of such floors before expiration of said certain time interval after the stop is made to prevent closure of said closure means for both of said compartments by their closure operating means.
66. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; stopping means responsive, when the car is set for travel in said given direction, to a registered one of said landing calls to cause operation of said mechanism to stop a certain one of said compartments at the floor for which such call is registered; and closure control means for each compartment operable incident to the stopping of that compartment at a floor in response to said landing call for that floor for causing operation of said closure operating means for that compartment to open said closure means for that compartment as such stop is made, said closure control means for a compartment, other than the one which is being stopped or has been stopped at a floor in response to said landing call for that floor, being responsive to the late registration of said landing call for the floor at which such other compartment is being or has been stopped to cause operation of said closure operating means for such other compartment to open the closure means for such other compartment, provided such late registration occurs before expiration of a certain time interval after such stop is made, and such late registered landing call, if maintained registered, being effective to control said closure control means for both compartments to prevent operation of said closure operating means for both compartments to close said closure means for both compartments so long as such landing call is maintained registered, said closure control means for each compartment acting upon expiration of a given time interval after discontinuance of registration of such late registered landing call to initiate operation of said closure operating means for that compartment to close said closure means for that compartment.
67. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment;

70 means for each compartment; closure control means for

each compartment operable, when the closure means for that compartment are open with that compartment stopped at a floor, to cause operation of said closure operating means for that compartment to close such closure means upon expiration of a closure time interval; and means for each compartment operable, when the closure means for that compartment are open with that compartment stopped at a floor during travel of the car in said given direction, in response to the registering and maintaining registered of said landing call for that floor to prevent closure of such closure means by said closure operating means for that compartment, so long as the registration is maintained, provided such registration takes place before the closure means for the other compartment in closing arrive within a certain distance of closed position.

68. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment operable, when the closure means for that compartment are open with that compartment stopped at a floor, to cause operation of said closure operating means for that compartment to close said closure means upon expiration of a closure time interval; means for each compartment operable, with that compartment stopped at a floor during travel of the car in said given direction, in response to the registering of said landing call for that floor to cause operation of said closure operating means for that compartment to open said closure means for that compartment and, if such closure means is already open or, upon opening thereof, to cause such closure means to remain open, so long as the registration is maintained; and means for preventing such opening and maintaining open of such closure means when such registration takes place after the closure means for the other compartment in closing arrive within a certain distance of closed position.

69. In an elevator installation; a plurality of floors; an elevator car having a pair of superimposed compartments

adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable, when the closure means for that compartment stopped at a floor, to cause operation of said closure operating means for that compartment to close such closure means upon expiration of a closure time interval; and means for each compartment operable, with that compartment stopped at a floor during travel of the car in said given direction, in response to the registering of said landing call for that floor to cause operation of said closure operating means for that compartment to open said closure means for that compartment, provided such registration takes place before the closure means for the other compartment in closing arrive within a certain distance of closed position.

70. In an elevator installation; a plurality of floors; an elevator car having a pair of superimposed compartments adapted to serve said floors; car actuating and stopping mechanism; a plurality of call registering means, one for each of said floors, for registering landing calls for a given direction of car travel; closure means for each compartment for controlling access thereto; closure operating means for each compartment; closure control means for each compartment operable, when the closure means for that compartment are open with that compartment stopped at a floor, to cause operation of said closure operating means for that compartment to close such closure means upon expiration of a closure time interval; and means for each compartment operable, with that compartment stopped at a floor during travel of the car in said given direction, in response to the registering of said landing call for that floor to cause operation of said closure operating means for that compartment to open said closure means for that compartment, provided such registration takes place before the closure means for the other compartment in opening arrive within a certain distance of open position.
